ABSTRACT

Method and apparatus for loosening soil from a mass of pervious cloth in which wash solution is applied to the rolls in the form of a plurality of reciprocable cascades to maintain the surfaces of the pervious cloth wet for a time sufficient to saturate the same; excess wash solution is continually drained from the mass of tightly wound rolls. The cloth articles are transported through a washing apparatus on a conveyor supported by a plurality of shafts extending through movable side walls of the washing apparatus and supported on bearings outside of the washing apparatus to prevent contact of the wash solution with the bearings supporting the shafts, orbital movement of the movable walls imparts similar orbital movement to the conveyor supported by the shafts to impart cycloidal movement to the cloth articles transported by the conveyor. The cloth articles are rinsed by directing a mist of gas and rinse liquid along a path normal to the articles therethrough to prevent puddles of the rinse liquid and the wash solution from forming thereon; thereafter, liquids are expressed from the articles by feeding the articles onto the side of a freely rotatable cylinder and therearound and upwardly between the cylinder and an associated roller, the cylinder and the roller are urged toward each other to press the articles therebetween to express the liquid therefrom. A dryer completes the drying of the articles.

CONTINUOUS WASHING APPARATUS

The present invention relates to methods and apparatus for the industrial processing of soiled fabric articles and more specifically to method and apparatus for loosening soil from a mass of randomly arranged, tightly wound, multi-layer rolls of pervious cloth by saturating each of the rolls to the innermost layer thereof with a wash solution, for preparing the wash solution therefor, for washing the soiled fabric articles by imparting a cycloidal motion thereto to disassociate the soil therefrom, for rinsing the wash solution from the fabric articles by forcing a rinse mist therethrough along a path normal thereto, for expressing excess liquid from the fabric articles by passing the articles upwardly between a freely rotatable cylinder and a drive roller and for drying the fabric articles.

It is an object of the present invention to provide method and apparatus for loosening soil from a mass of pervious cloth comprising transporting the mass of pervious cloth on a foraminous conveyor through a crib surrounding the conveyor and applying a wash solution to the mass of tightly wound rolls to maintain the surfaces thereof wet for a time sufficient to saturate each of the tightly wound rolls to the innermost layer thereof, while continually draining excess wash solution from the mass of tightly wound rolls through the foraminous conveyor whereby to loosen the soil from the cloth.

It is another object of the present invention to provide method and apparatus of the type set forth in which the wash solution is applied to the mass of pervious cloth as a cascade, the cascade being reciprocable along a predetermined path overlying the conveyor.

It is a further object of the present invention to provide method and apparatus of the type set forth in which the drained wash solution is collected and make-up wash solution is added to the collected wash solution and recirculated to the cascade of wash solution.

It is a still further object of the present invention to provide method and apparatus of the type set forth in which a plurality of reciprocable cascades of wash solution are provided, the plurality of cascades defining a corresponding number of zones through which the mass of pervious cloth is transported.

It is another object of the present invention to provide apparatus and method of the type set forth in which the temperature of the cascades of wash solution applied to the mass of pervious cloth is controlled thereby to produce a thermal shock therein.

A still further object of the present invention is to provide apparatus for preparing wash solution comprising an elongated cylinder providing therein a mixing chamber, a reservoir for holding freshly prepared wash solution disposed about the bottom of the cylinder, the cylinder being in communication with the reservoir to supply freshly prepared wash solution thereto, a stirrer disposed in the cylinder and including a plurality of members extending outwardly from the stirrer, a plurality of baffles extending from the inner walls of the cylinder, the baffles and the outwardly extending members cooperating upon rotation of the stirrer to provide a mixing action in the cylinder, a water supply pipe for introducing water into the cylinder tangentially to the inner wall thereof, thereby to produce a vortex of the water inside the cylinder, first control means associated

with the water supply pipe for controlling the flow of water therethrough, an additive supply in communication with the cylinder for supplying an additive to the cylinder, second control means associated with the additive supply for controlling the amount of the additive supplied therefrom to the cylinder for mixing with the vortex of water, a pump for pumping wash solution from the reservoir, and means responsive to the level of wash solution in the reservoir for operating the first and second control means to control the amount of water and additives added to the cylinder, whereby to maintain constant the level of wash solution in the reservoir while the pump is operative to pump wash solution therefrom.

Another object of the present invention is to provide apparatus for washing soiled articles comprising a tank for holding a wash solution, the tank including movable side walls, a conveyor for transporting the soiled articles through the tank, a plurality of shafts extending through the movable side walls of the tank for supporting the conveyor, the shafts being mounted on bearings outside of the tank, a plurality of seals between the shafts and the movable side walls of the tank for preventing contact of the bearings with the wash solution thereby to prevent the wash solution from removing lubrication from the bearings, drive mechanism for imparting orbital movement to the side walls and thereby to the shafts, whereby rotation of the shafts and the orbital movement imparted thereto by orbital movement of the movable side walls impart cycloidal motion to the articles transported by the conveyor with respect to the wash solution in the tank to disassociate the soil from the articles.

A still further object of the present invention is to provide apparatus for rinsing wash solution from fabric articles comprising a rinsing unit including a pressure chamber for generating a mist of a gas and a rinse liquid, a rinse conveyor for transporting the articles along a predetermined path adjacent to the rinsing unit, a nozzle for the rinsing unit including two spaced-apart walls defining therebetween a passage through which the mist is forcibly expelled from the pressure chamber and through the articles on the conveyor, the portions of the walls adjacent to the exit end of the nozzle being disposed substantially normal to the predetermined path to prevent puddles of the rinse liquid and the wash solution from forming on the associated article and thus decreasing the quantity of mist forced therethrough, and a collecting vessel disposed adjacent to the rinse conveyor in position to receive the mist and wash solution carried thereby passing through the articles, whereby to rinse the wash solution from the articles.

Still another object of the present invention is to provide apparatus for expressing liquids from a wet fabric article comprising a freely rotatable cylinder arranged for rotation about a first essentially horizontal axis, a driving roller arranged for rotation about a second essentially horizontal axis in substantially horizontal alignment with and substantially parallel to the first axis, first feed structure for feeding the fabric article onto the cylinder on the side thereof opposite the roller and downwardly and around the cylinder and upwardly between the cylinder and the roller, and motor means for urging the cylinder and the roller toward each other

to press the fabric article disposed therebetween for expressing the liquid therefrom, whereby to express liquid from the article downwardly between the portion of the article disposed on the cylinder and the adjacent exposed side of the roller.

A further object of the present invention is to provide apparatus for expressing liquids from a plurality of series of the fabric articles arranged in side-by-side relationship, the apparatus comprising a plurality of freely rotatable cylinders equal in number to the plurality of series of fabric articles and arranged in an end-to-end relationship for rotation about a first essentially horizontal common axis, a first plurality of driving rollers corresponding in number to a first set of alternate ones of the cylinders and arranged for rotation about a second essentially horizontal common axis disposed on one side of the cylinders and in substantial horizontal alignment with and substantially parallel to the first common axis, a second plurality of driving rollers corresponding in number to a second set of alternate ones of the cylinders and arranged for rotation about a third essentially horizontal common axis disposed on the other side of the cylinders and in substantial horizontal alignment with and substantially parallel to the first and second common axis, a first plurality of first feed structures equal in number to the first set of cylinders for feeding the corresponding series of fabric articles respectively onto the cylinders in the first set of cylinders on the sides thereof opposite the associated rollers and downwardly and therearound and upwardly between the cylinders in the first set of the cylinders and the associated rollers, a second plurality of first feed structures equal in number to the second set of cylinders for feeding the corresponding series of fabric articles respectively onto the cylinders in the second set of cylinders on the sides thereof opposite the associated rollers and downwardly and therearound and upwardly between the cylinders in the second set of cylinders, first motor means for urging the first plurality of driving rollers toward the first set of cylinders to press the fabric articles disposed therebetween for expressing the liquid therefrom, second motor means for urging the second plurality of driving rollers toward the second set of cylinders to press the fabric articles disposed therebetween for expressing the liquid therefrom, whereby to express liquid from the articles downwardly between the portions of the articles disposed on the associated cylinders and adjacent exposed side of the associated roller.

The invention, both as to its organization and method of operation, together with further objects and advantages thereof, will best be understood by reference to the following specification taken in connection with the accompanying drawings in which:

FIG. 1 is a diagrammatic illustration with certain portions in section of a four-zone apparatus embodying the portion of the present invention for applying wash solution to the mass of randomly arranged, tightly wound, multi-layer rolls of pervious cloth to saturate each of the tightly wound rolls to the innermost layer thereof, whereby to loosen the soil therefrom;

FIG. 2 is a diagrammatic illustration with certain portions in section of apparatus embodying the portion of the invention for disassociating soil from soiled fabric articles by imparting cycloidal motion thereto as the ar-

ticles are transported through a wash solution and the portion of the invention for rinsing the entrained wash solution from the fabric articles;

FIG. 3 is a diagrammatic illustration with certain portions in section of apparatus embodying the portion of the invention for further rinsing the fabric articles for expressing excess liquid therefrom by passing the wet article upwardly between a freely rotatable cylinder and a driven roller and for drying the fabric articles by passing the articles past a plurality of gas burners;

FIGS. 4 to 6 are diagrammatic views of the apparatus shown in FIG. 1 to more fully illustrate the variable capacity thereof;

FIG. 7 is a side elevational view of the apparatus shown in FIG. 1 and further showing the position of the wash solution supply mechanisms defining the four zones, the heaters therefor and the apparatus for adding make-up solution thereto;

FIG. 8 is a plan view of the apparatus shown in FIG. 7;

FIG. 9 is an enlarged side elevational view partly broken away of a portion of the apparatus shown in FIG. 7;

FIG. 10 is an enlarged view of a portion of the conveyor shown in FIG. 1;

FIG. 11 is a view partly in section of a portion of the conveyor shown in FIG. 10 taken along line 11-11;

FIG. 12 is an enlarged side elevational view of a portion of the apparatus shown in FIG. 7;

FIG. 13 is a sectional view of the apparatus shown in FIG. 12 taken along line 13-13 and particularly showing the position of the drive for the wash solution supply mechanism and the spatial relationship of the endless conveyor belt;

FIG. 14 is a sectional view of the apparatus shown in FIG. 13 taken along line 14-14;

FIG. 15 is an enlarged view partly in section of the first mixing stage shown in FIG. 7 and showing the spatial relationship between the mixing chamber, the additive supplies and the reservoir;

FIG. 16 is a view partly in section of the supply mechanism for applying wash solution to the mass of tightly wound rolls and the drive mechanism for providing reciprocal movement thereto;

FIG. 17 is a side elevational view partly broken away and partly in section of the mechanism shown in FIG. 16 taken along line 17-17 and particularly showing how wash solution is supplied thereto;

FIG. 18 is a plan view of the supply mechanism shown in FIG. 16;

FIG. 19 is an elevational view of a sectional supply mechanism for applying wash solution to the mass of tightly wound rolls without the drive mechanism shown in FIG. 17;

FIG. 20 is a sectional view particularly showing the trough of the mechanism shown in FIG. 19 taken along line 20-20;

FIG. 21 is a side elevational view of the orbital washer showing the tortuous path provided for the soiled fabric articles and the orbitable portion of the tank wall;

FIG. 22 is a plan view of the orbital washer shown in FIG. 21;

FIG. 23 is a view partly in section of a portion of the orbital washer shown in FIG. 21 taken along line 23-

23 and particularly showing shafts extending through the orbitable tank wall and supporting the wire mesh conveyor;

FIG. 24 is a view partly in section of a portion of the orbital washer shown in FIG. 21 taken along line 24—24 and showing a crankshaft extending through the orbitable tank wall and supported on bearings external of the tank;

FIG. 25 is a sectional view of the orbital washer shown in FIG. 21 and more particularly illustrating the conveyor assembly for transporting the soiled cloth through the tank;

FIG. 26 is an enlarged side elevational view of the conveyor shown in FIG. 25 showing the conveyor at the loading end of the orbital washer;

FIG. 27 is an enlarged side elevational view of the conveyor shown in FIG. 25 showing the conveyor at the discharge end of the orbital washer;

FIG. 28 is an enlarged side elevational view partly in section of the conveyor, the support therefor and a portion of the drive mechanism therefor;

FIG. 29 is an enlarged side elevational view showing the laminar relationship between the conveyor belts and the soiled articles supported therebetween;

FIG. 30 is an enlarged view of the circled portion of FIG. 29 particularly showing the flexing of the soiled article as it is transported through the washer;

FIG. 31 is an enlarged plan view of a wire mesh suitable for use as one of the conveyor belts;

FIG. 32 is a diagrammatic view of the eccentric portions of a crankshaft supporting the orbitable tank wall, rotation of the crankshaft providing orbital movement to the tank wall;

FIG. 33 is a side elevational view of the drive mechanism for the conveyor for the siphon-surge rinser with the rinsing and collecting units removed for clarity;

FIG. 34 is a front elevational view of the rinser shown in FIG. 33;

FIG. 35 is a side elevational view partly in section of the rinser showing the conveyor, the rinsing units and collecting units therefor;

FIG. 36 is an end elevational view of a rinsing unit partly in section showing the relative positions of the pressure chamber, the conveyor and the collecting vessel;

FIG. 37 is a sectional view of a portion of the apparatus shown in FIG. 36 taken along line 37—37 showing the relationship of the nozzle and conveyor;

FIG. 38 is an enlarged sectional view of a portion of the apparatus shown in FIG. 37;

FIG. 39 is a perspective view of a portion of the extractor apparatus showing the end-to-end relationship of the drums and the relationship of the driven rollers with the drums;

FIG. 40 is a plan view of a series of cylinder and roller units arranged as shown in FIG. 39 and adapted to receive ten lanes of fabric articles arranged in a side-by-side relationship;

FIG. 41 is a sectional view of the apparatus shown in FIG. 40 taken along line 41—41 showing one of an alternate set of drums, the associated driven rollers and the mechanism for feeding the lanes of articles thereto;

FIG. 42 is a sectional view of the apparatus shown in FIG. 40 taken along line 42—42 showing one of the

other alternate set of drums, the associated driven rollers and the mechanism for feeding the lanes of articles thereto;

FIG. 43 is an enlarged sectional view partly in elevation of the freely rotatable drum shown in FIG. 42 taken along line 43—43; and

FIG. 44 is an enlarged side elevational view partly in section of the roller and bearing shown in FIG. 42 taken along line 44—44 showing the relationship between the rollers and the bearings disposed therebetween.

There is illustrated and explained in detail hereinafter a washing-rinsing-extracting-drying system including a soil-loosening apparatus 105, an orbital washer 525, a rinsing unit 710, a time-delay conveyor 905, a further rinsing unit 710a, an extractor system 925 and a dryer 1025. In operation, randomly arranged, tightly wound, multi-layer rolls of pervious cloth 101 are introduced into the soil-loosening apparatus 105 and saturated therein to the innermost layer of the rolls 101 for a time sufficient to loosen the soil therefrom, from there the rolls 101 are transported to the orbital washer 525 where the rolls are unwound into lanes of flatwork 675 arranged in side-by-side relationship and transported along a tortuous path through the washer 525 wherein soil is removed from the flatwork 675, thereafter the flatwork 675a is transported to the rinser 710 for rinsing the wash solution therefrom, after a bleach is applied thereon at 900 and the flatwork 675b is transported to a time-delay conveyor 905 which transports the flatwork 675b to another rinser 710a. After the flatwork 675c exits from the rinser 710a, a sour spray is applied thereto at 900a and thereafter the flatwork 675c is fed to an extractor 925 in which excess liquid is expressed therefrom, from which the flatwork 675d is fed to a dryer 1025 for further drying to provide the finished flatwork 675e.

As shown in the drawings, and particularly in FIGS. 1, 7 to 9, and 12 to 14, there is provided a soil-loosening apparatus 105 including a crib 106 for retaining the mass 102 of tightly wound rolls 101, the crib 106 having two elongated spaced-apart upstanding side walls 107 and a top wall 109 extending thereover, the top wall 109 being corrugated and having raised portions 110, the portions 110 extending generally horizontally, lower portions 111, the lower portions 111 being vertically spaced from the raised portions 110 and also extending generally horizontally and parallel to the raised portions 110 and connecting portions 112, the connecting portions 112 interconnecting the raised portions 110 and the lower portions 111. The crib 106 is also provided at spaced-apart intervals with cross-ties 113 for increasing strength and rigidity of the crib 106, the cross-ties 113 being tubular in shape and extending transverse to the longitudinal axis of the crib 106, the cross-ties 113 also providing support with angle brackets 114 for the top wall 109.

The crib 106 also includes at spaced-apart points along the side walls 107 corresponding to the positions of the cross-ties 113 a plurality of support columns 115, the support columns 115 being positioned exterior to each side wall 107 and each column 115 being aligned in a plane transverse to the longitudinal axis of the crib 106 with another column 115, the columns being connected to the walls 106 as hereinafter explained. The

columns 115 are identical and therefore only one will be described in detail, the column includes a rectangular post 116 supported by a pair of L-shaped plates 117, the plates 117 being spaced apart and suitably secured to each side of the post 116 such as by welding. The L-shaped plates 117 have a vertical abutment surface 118 on the vertical part of the "L", an upper abutment surface 119 on the horizontal part of the "L" and a lower abutment surface 120 also on the horizontal part of the "L". As seen from the drawings, the support columns 115 are placed at evenly spaced-apart points along the crib 106, at each point two columns 115 are provided along a plane normal to the longitudinal axis of the crib 106 for a purpose to be hereinafter explained, it being realized that this is but the preferred embodiment of the invention, other support arrangements being considered within the scope of the present invention.

Each of the support columns 115 rests on a sole plate 125, the sole plates 125 extending parallel to the longitudinal axis of the crib 106 and being spaced apart a distance equal to the distance between opposed support columns 115. Each of the sole plates 125 is in the form of an I-beam having an upper horizontal flange 126 and a lower horizontal flange 127 interconnected by a vertically extending bight 128, the upper flange 126 having an abutment surface 129 thereon providing support for the lower abutment surfaces 120 on the bottom of the two L-shaped plates 117 of each and every support column 115. The sole plates 125 have on the lower horizontal flange 127 thereof an upper abutment surface 130 for a purpose hereinafter explained and a lower abutment surface 131, the lower abutment surface 131 abutting longitudinally extending grouts 135, the grouts 135 being positioned on the floor or ground 136; the grouts 135 are inclined from the left-hand end of the crib 106 to the right-hand end, as viewed in FIG. 7, for a purpose to be hereinafter explained.

Each of the support columns 115 have attached thereto two vertically spaced-apart horizontally extending beams 140, the beams 140 serving to connect each support column 115 with a vertically positioned support beam 141. Interposed between the vertical beams 141 and the side walls 107 of the crib 106 are a plurality of vertically spaced-apart horizontal and longitudinally extending supports 142, the supports 142 being in the form of tubes or pipes and being welded to the side walls 107 and the vertical beams 141, thereby to provide suitable support for the side walls 107 and the required connection between the walls 107 and the support columns 115. Stainless steel liners 143 extending the entire length of the crib 106 are suitably connected to the side walls 107 for a purpose hereinafter to be explained, the stainless steel liners 143 being secured to the walls 107 by a plurality of U-shaped brackets 144, each of the brackets 144 having an inner leg 145, an outer leg 146 and a bight 147 interconnecting the legs, the brackets 144 being positioned over the stainless steel liners 143 and the side walls 107 at appropriate spaced-apart points and suitably secured thereto.

Near the top of the crib 106 at spaced-apart points therealong are a plurality of sliding panels 150, the panels 150 being suitably held in place at the top thereof by a continuous U-shaped channel 151 spaced

along the length of the crib 106 and each having two spaced-apart legs 151a depending from a horizontally positioned web 152, the legs 151a being spaced apart a distance sufficient to provide for sliding of the panels 150. The channel 151 is connected to one of the cross-ties 113 and depends downwardly therefrom. The panels 150 are held in place at the bottom thereof by two Z-shaped angle members 153, the Z-shaped angle members being positioned one on each side of the crib 106, each member 153 including a vertical attachment portion 154 suitably connected to the inner legs 145 of the U-shaped brackets 144, the angle members 153 further including a diagonal member 156 connecting the vertical attachment portion 154 with an upper vertical attachment portion 155, the upper vertical attachment portion 155 providing for the positioning and the support of the sliding panel 150. At spaced-apart points along the panel 150 are inner panels 157 abutting and sliding with the panel 150, the panels 157 are maintained in place at the top thereof by the U-shaped brackets 151 and at the bottom thereof by a plurality of tension members 158, the tension members 158 being provided with an attachment portion 159 suitably secured to the diagonal member 156 and a continuous rod 160 in tensioning contact with the inner panels 157. The sliding panels 150 are provided at spaced-apart points thereon with handles or knobs 161, the sliding panels 150 providing for easy visual access to the inside of the crib 106 during operation.

The crib 106 is further provided with a loading area 170, as viewed in the left-hand portion of FIG. 1 for loading the rolls 101 into the crib 106, the loading area 170 including two spaced-apart upstanding side walls 171, the side walls 171 being connected by a transversely extending end wall 172, the height of the side walls 171 being adapted to provide for easy manual loading of the rolls 101 into the crib 106. The side walls 171 and end walls 172 are mounted on a horizontally extending platform 175, the platform 175 having a work surface 176 supported by a vertical wall 177. The crib 106 is also provided at the right-hand portion thereof, as viewed in FIG. 1, with a discharge area 180, the discharge area 180 including spaced-apart upstanding side walls 181, the side walls 181 having vertical edges 182 and radial edges 182a and further including outwardly extending flanges 183 attached to and integral with the vertical edges 182, the flanges 183 being for a purpose hereinafter to be explained. The entire crib 106 and conveyor 190 are inclined, as hereinbefore stated, from the loading area 170 to the discharge area 180, the incline being generally uniform and at a rate of about one-fourth inch vertical displacement for every foot of length.

There is also provided a conveyor system 190 for transporting the mass 102 of rolls 101 through the crib 106 from the loading area 170 to the discharge area 180, the conveyor system 190 including two spaced-apart tracks 195, each in the form of an I-beam to provide support as hereinafter explained, the tracks 195 each including a lower generally horizontal flange 196 having an abutment surface 197 resting on the abutment surface 119 of each L-shaped member 117 and an upper generally horizontal flange 198 having an abutment surface 199, interconnecting the lower flange 196 and the upper flange 198 is a bight 201. On the abut-

ment surface 199 of each upper flange 198 rests a track bar 205 extending from the loading area 170 to the discharge area 180, the track bars 205 being rectangular in shape and each having an upper abutment surface 206 and a lower abutment surface 207, each of the lower abutment surfaces 207 being suitably connected to the corresponding upper abutment surface 199 of the associated upper flange 198.

The conveyor system 190 further includes a plurality of spaced-apart slats 211 in the form of tubes, the slats 211 being part of an endless conveyor chain 215, the chain includes a plurality of rollers 216 rotatably mounted on shafts 217 adjacent each end thereof, the rollers 216 supported by and in rolling contact with the respective track bar 205. Each of the rollers 216 is held between two spaced-apart links 220, the links 220 having side walls 221, the side walls 221 having therein apertures 222 for receiving therethrough a shaft 217 for rotatably supporting the associated roller 216. The side walls 221 of the links 220 further include horizontally extending flanges 223, the horizontally extending flanges 223 are provided with apertures therein (not shown) for mounting the transversely extending tubular slats 211 onto the links 220 by means of headed bolts 225 and square nuts 226, the outermost link 220 of each two links holding a roller 216 therebetween having a flange 223 extending toward the end of the slat 211, the innermost link 220 having a flange 223 extending in the opposite direction. The tubular slats 211 may be provided with a corrosion-resistant vinyl plastic coating for a purpose hereinafter explained.

The endless conveyor chain 215 is supported at the loading area 170 by an idler sprocket 230 rotatably mounted on a shaft 231, suitably journaled in spaced-apart mounting plates 232, the mounting plates 232 resting on the I-beam 125. Adjacent the discharge area 180 is a motor 235 suitably connected to a gear reducer 236 to provide rotation of a drive sprocket 238 by means of a drive shaft 237, the motor 235 providing the driving force for rotation of the endless conveyor chain 215. As may be seen from the Figures and the description herein, there is provided an endless conveyor chain 215 which travels in a continuous loop, support for the top portion of the loop being provided by tracks 205 and support for the bottom part of the loop being provided by the abutment surface 130 of the low I-beam 125. The outwardly directed flanges 183 in the discharge area 180 provide rigidity to the side walls 181 while the platform 175 and supports 177 protect the operators from contact with the moving slats 211 at the loading area 170.

As may be seen by particular reference to FIGS. 13, 14 and 18 to 20, there is also provided a wash solution-supply system 240 including a plurality of troughs 245. The troughs 245 are spaced-apart longitudinally along the crib 106, as shown particularly in FIG. 1, each trough 245 extends generally transversely to the longitudinal axis of the crib 106 from one side wall 107 to the other and includes a V-shaped wall 246 having integral therewith two inwardly, diagonally downwardly turned flanges 247, the troughs 245 being provided with end plates 248 and end cap 249. All of the troughs 245 are identical in construction, however, the trough 245 in the second zone, as hereinafter described and shown in relation to the other troughs 245, is im-

mediately connected to the mechanism providing the reciprocal movement of all the troughs 245 and is particularly illustrated in FIGS. 16, 17 and 18.

The above-mentioned trough 245 is held between two spaced-apart mounting plates 255, each of the mounting plates 255 having at the bottom thereof a nut 256 and a headed adjustment screw 257 therein, the screw 257 having a shank portion 258 in contact with the bottom of the trough 245. The trough 245 is suitably secured to the mounting plates 255 by headed bolts 261 positioned in two vertically spaced-apart slots 262 in each of the mounting plates 255. In each of the mounting plates 255, spaced above the end cap 249, are apertures (not shown) through which axles 266 extend, the axles 266 are aligned along the same horizontal axis and are each a bearing 265 at one end thereof and carry at the other end thereof a roller 267, the rollers 267 being positioned exterior of the mounting plates 255 to provide movement of the plates 255 and hence the trough 245 mounted therebetween.

On either side of the crib 106 there is provided a channel-shaped track 270, the track 270 including an upper flange 271, a lower flange 272 and a web 273 interconnecting the upper and lower flanges, the track 270 extending the entire length of the crib between the loading area 170 and the discharge area 180 and being suitably connected to the cross-ties 113 by angle irons 275, each of the angle irons 275 having a vertical portion 276 suitably attached to the web 273 of the track 270 and a horizontal portion 277 suitably attached to the cross-ties 113. Disposed below the bearings 265 on each side of the trough 245 there are two connecting tie rods 280, the tie rods 280 being suitably secured to the mounting plates 255 such as by welding, the tie rods 280 extend longitudinally of the crib 106 and serve to interconnect all of the troughs 245, for a purpose hereinafter to be explained.

Positioned between the two mounting plates 255 at the top thereof is a header 285, the header 285 being sealably connected to the left-hand mounting plate, as viewed in FIG. 17, and sealably connected to the right-hand mounting plate 255, as seen in FIG. 17, the right-hand mounting plate 255 having therein an aperture (not shown) providing communication between the header 285 and the supply of a wash solution. Downwardly depending from the header 285 is a supply pipe 286, the supply pipe 286 having a vertical section 287 suitably connected to the header 285 by a fitting 288, the supply pipe 286 further including a horizontal section 289 lying along the bottom of the trough 245; connecting the vertical section 287 and the horizontal section 289 is an elbow section 291.

Disposed above and connected to the header 285 is a yoke 295, the yoke 295 including a generally rectangular plate 296 having at the bottom thereof two diagonally inwardly and downwardly inclined edges 297 connected by an arcuate edge 298 having a radius of curvature the same as the radius of curvature of the outside surface of the header 285, the edge 298 of the plate 296 being suitably secured to the header 285, such as by welding. The generally rectangular plate 296 is provided with an elongated slot 299, the slot 299 being positioned along the vertical midplane of the plate 296 and extending generally downwardly from the top of the plate 296, the plate 296 being closed at

the top thereof by a yoke cap 301 extending across the slot 299 and suitably secured to the plate 296 by bolts 302. There is also provided a yoke drive wheel 305 for effectively connecting the yoke 295 with the drive mechanism, the wheel 305 including a headed shaft 306 mounted in the slot 299 of the yoke 295 from the right-hand side as viewed in FIG. 17. The headed shaft 306 has a large diameter portion 307 and a small diameter portion 308, the large diameter portion 307 fitting within the slot 299 and adapted to move vertically within the slot 299, the portion 307 carrying thereon spaced-apart discs 309 for retaining the shaft 306 within the slot 299 and preventing movement thereof transverse to the longer dimension of the slot.

There is also provided a yoke drive assembly 310 including a pair of mounting brackets 311, the mounting brackets 311 including a body portion 312 having an arcuate edge 313 at the bottom thereof, the arcuate edge 313 being suitably secured to the cross-ties 113 in the center thereof, as shown in FIG. 13. Only two cross-ties 113 carry the yoke drive assembly 310, there being one drive assembly 310 to provide movement for all of the troughs 245. Suitably secured to the mounting brackets 311, which extend diagonally inwardly from the cross-ties 113, are bearings 315 secured to the mounting bracket 311 by bolts 316, the bearings 315 are positioned on both sides of the brackets 311. Suitably journaled in the bearings 315 closest to the loading area 170 is an idler sprocket shaft 318 carrying thereon an idler sprocket 319, the sprocket 319 being on the right-hand side of the mounting bracket 311.

On the left-hand side of the crib 106 as viewed in FIG. 13 is a motor 321. Coupled to the motor 321 is a gear reducer 322, a shaft 323 extending therefrom and driven by the motor 321, the driven shaft 323 being suitably connected thereto by a coupling 324. The drive shaft 323 extends from the motor 321 transversely of the longitudinal dimension of the crib 106 to the mounting brackets 311 which are mounted at the middle of the cross-ties 113. At the distal end of the drive shaft 323 from the motor 321 is a drive sprocket 329, the sprocket being suitably secured to the drive shaft 323 for rotation therewith and carrying thereabout a chain 330, the chain 330 forming an endless loop between the drive sprocket 329 and the idler sprocket 319. As may be seen from the Figure, the smaller diameter portion 308 of the headed shaft 306 extends through the chain 330 and therefore as the chain 330 travels in its closed path as viewed in FIG. 16, the shaft 306 is carried therewith and therefore also the yoke 295. When the shaft 306 and the yoke 295 encounter either the idler sprocket 319 or the drive sprocket 329, the shaft 306 travels downwardly or upwardly in the slot 299 as the case may be, particularly as seen in the phantom view in the left-hand side of FIG. 16. As may be seen, therefore, the troughs 245 travel in a reciprocal path as defined by the endless chain 330, all the troughs being connected by the connecting tie rods 280 simultaneously to travel reciprocal paths overlying the slots 211 along the length of the crib 106 parallel to the longitudinal axis thereof. Each of the reciprocal paths defined by the troughs 245 forms a zone through which the mass 102 of rolls 101 is transported, the purpose being hereinafter explained.

A temperature gage 335 is connected to an inlet pipe 336 leading to the header 285. Depending from the inlet pipe 336 is a connecting pipe 337, the connecting pipe 337 having a vertically downwardly extending portion 338 and an angle portion 339, the end of the angle portion 339 being connected to a flexible hose 340. While the Figures show only one temperature gage, it is to be understood that each of the sections may be provided with a temperature gage. As may be realized, any of the particular sections of the crib 106 may be provided with the drive motor 321, however, it is shown here that the second section from the loading area 170 has the motor. As seen particularly in FIG. 19, the other sections of the crib 106 are provided with troughs 245 suitably mounted between two mounting plates 345, each of the mounting plates 345 having at the bottom thereof a nut 346 carrying therein a headed adjustment screw 347 having a shank 348, the shank 348 being in contact with and providing adjustment for the trough 245. Each of the troughs 245 is suitably connected to the mounting plates 345 by headed bolts 351 in two slots 352 provided in the mounting plates 345. The mounting plates 345 are carried by the rollers 267 and carry thereon angle brackets 355, the angle brackets 355 having a vertical portion 356 suitably secured to the mounting plates 345 such as by welding and a horizontal section 357 suitably supporting a support plate 358. The support plates 358 each carry thereon a supply pipe 361, the supply pipes 361 each includes a horizontal pipe 362 suitably secured to the associated support plate 358 by two U-shaped brackets 363 having threaded ends for receiving fastening nuts 364 thereon. Connected to the left-hand portion of the horizontal pipe 362, as seen in FIG. 19, is an elbow 367 providing connection between the horizontal pipe 362 and a vertical feed pipe 368, the vertical feed pipe 368 terminating within the trough 245. On the right-hand portion of the supply pipe 361 is a vertical part 371 and a stopper 372, the vertical part 371 of the supply pipe 361 being connected to a flexible hose 340 by a connecting pipe 377. As best seen in FIG. 20, wash solution 375 introduced into the troughs 245 overflows therefrom and down the sides 246 thereof the flanges 247 providing for smooth flow therealong to form a plurality of cascades of wash solution 376 which fall onto the mass 102 of tightly wound rolls 101 being transported through the crib 106 by the conveyor system 190.

As best seen in FIG. 13, there is disposed below the tubular slats 211 supporting the mass 102 of tightly wound rolls 101, a drip pan 380, the drip pan 380 being inclined downwardly from the left-hand side of the crib 106 to the right-hand side of the crib. The drip pan 380 consists of a plurality of sheets 385, each of the sheets 385 being roughly the same length as the zones defined by the reciprocal paths of the troughs 245, the drip pan 380 having at spaced-apart points thereon a plurality of low ribs 381 and at the outermost ends thereof high ribs 382. Each of the high ribs 382 is formed by an upwardly extending portion 386 of one of the sheets 385 and a hook-shaped portion 387 of the adjacent sheet 385, the upwardly extending portion 386 fitting with the hook-shaped portion 387 to form the high rib 382. The drip pan 380 also includes an attachment flange 383 on the left-hand side thereof which is attached to

the abutment surface 199 of the upper flange 198 of I-beam 195.

On the right-hand side of the crib 106, as viewed in FIG. 13, there is a collecting trough 390, the collecting trough 390 extending the length of the crib 106 and including an upstanding side wall 391 which receives therein a lip 384 connected to the drip pans 380, the collecting trough 390 further including a second upstanding side wall 392 spaced from the wall 391 and suitably attached to the I-beam 195; a curved bottom portion 393 interconnects the upstanding side walls 391 and 392. Disposed horizontally across the trough 390 and suitably connected to the upstanding side walls 391 and 392 is a screen filter 395, the filter 395 being disposed below the lip 384 of the drip pans 380 for filtering the drained wash solution collected in the drip pan 380. Depending from the curved bottom portion 393 of the collecting trough 390 at spaced-apart points therealong are a plurality of drain hoses 398 suitably secured to the trough 390 by fittings 397, each of the drain hoses 398 leading to a collecting basin 400 or 421.

As may be seen from the above description, wash solution 375 introduced into each of the troughs 245 overflows therefrom to form cascades 376 which fall onto the mass 102 of tightly wound rolls 101 transported through the crib 106 by the conveyor system 190. As the wash solution 375 contacts the multi-layer rolls 101, the rolls 101 become saturated to the innermost layer thereof with the wash solution 375, excess wash solution falling from the rolls 101 through the tubular slats 211 of the conveyor system 190 onto the drip pan 380 and then into the collecting trough 390, the trough 390 being divided into sections to prevent mixing of the wash solution collected from each zone. From the collecting trough 390 the wash solution flows into the collecting basins 400 and 421.

The collecting basin 400 and the mixing station 410 are adjacent the loading area 170 and are different from the sectional mixing stations 420 and the collecting basins 421 therefor, the collecting basin 400 and mixing station 410 for collecting wash solution draining from the rolls 101 and providing make-up solution draining from the rolls 101 and providing make-up solution to be added thereto to maintain constant the cascade 376 in the first zone being hereinafter described. The collecting basin 400 may be entirely buried within the ground 136 or it may extend partly outwardly therefrom, the basin 400 being generally cylindrical in shape and including a side wall 401 and a bottom wall 402, the side wall 401 terminates in its uppermost edge in a lip 403, the basin 400 serving as a reservoir for the wash solution as hereinafter explained. Upwardly disposed from the basin 400 is a horizontally extending platform 405, the platform 405 having therein a central aperture 406 and a motor stand 407 spaced from the platform 405 and parallel thereto, the stand 407 being positioned over the aperture 406; a plurality of downwardly extending legs 408 connect the stand 407 with the platform 405 and support the stand thereon. The first wash solution mixing station 410 further includes an inner mixing tube 415 and an outer return tube 416 disposed concentrically about the inner tube 415 to maintain the liquid in the mixing tube 415 at a predetermined level. The outer return tube

416 is closed at the bottom end thereof by base plate 417, the inner mixing tube 415 being open at the bottom thereof is positioned with the bottom thereof spaced above the bottom of the outer tube 416 and supported thereat by supports 418 thereby providing communication between the inner mixing tube 415 and the outer return tube 416, it being noted that the upper end of the inner mixing tube 415 extends above the upper end of the outer return tube 416 and the liquid level in the tube 415 is determined by the point at which liquid flows from the tube 416. A motor 430 positioned on a motor stand 407 is connected to a gear reducer 431, the gear reducer 431 being in turn connected to a stirrer 435, the motor 430 and gear reducer 431 cooperating to provide for rotation of the stirrer 435. The stirrer 435 including a longitudinally downwardly extending shaft having thereon a plurality of spaced-apart mixing pins 436 transversely extending therefrom. Attached to the inner wall of the inner mixing tube 415 extending transversely to the longitudinal axis of the tube 415 are a plurality of spaced-apart mixing pins 437, the mixing pins 437 being alternately positioned with the mixing pins 436 extending from the stirrer 435. The mixing pins 437 acting as baffles to provide with the mixing pins 436 on the stirrer 435 upon rotation thereof mixing action within the tube 415.

Disposed on the platform 405 about the aperture 406 are a plurality of liquid additive storage containers 440 and 441, each of the containers 440 and 441 have an outlet 445 and 446 respectively extending therefrom in communication with the inner mixing tube 415. Connected to the outlets 445 and 446 are solenoid valves 448 and 449 respectively for controlling the amount of liquid additive flowing from the containers 440 and 441 through the outlets 445 and 446 to the mixing tube 415. Also disposed on the platform 405 is a solid additive storage hopper 450, the hopper 450 including a triangular front wall 451 inclined inwardly and downwardly toward the center of the platform 405 and spaced-apart triangular side walls 452 also inwardly and downwardly inclined, the storage hopper 450 further including a straight back wall 453 and an outwardly extending lip 454 disposed about the top edge of the hopper 450. The bottom of the hopper 450 contains an aperture (not shown) leading to a corresponding aperture (not shown) in a feed screw housing 460, the feed screw housing 460 resting on the platform 405 intermediate the platform and the hopper 450 and having a closed end 461 extending over the aperture 406 and having an opening 462 in the bottom thereof in registry with the aperture 406 in the platform 405. Disposed within the housing 460 is a shaft 465 carrying thereon a wormscrew 466 for feeding the solids from the hopper 450 into the mixing tube 415. The shaft 465 passes through a mounting block 467 and a bearing assembly 468, the entire mounting block and bearing assembly rests on a platform 469. As seen in FIG. 9, a motor 470 drives a shaft 471 connected to a drive sprocket 472; an endless belt 474 connects the drive sprocket 472 with a sprocket 473 mounted on the shaft 465, thereby to provide rotation of the wormscrew 466 upon rotation of the shaft 465 thereby to transmit solids 477 from the hopper 450 into the mixing tube 415.

There is further provided a water inlet pipe 480 and a solenoid valve 481 for controlling the amount of water flowing therethrough, the inlet pipe 480 being fixed to the inner wall of the mixing tube 415 to introduce thereinto water tangentially to the inner wall of tube 415 to form a vortex therein, thereby to provide improved flushing action of the water to keep the walls 415 clean.

As may be seen, freshly prepared wash solution 485 of the water mixed with the additives in tube 415 flows downwardly through tube 415 from the bottom thereof into tube 416 and upwardly therethrough to overflow therefrom and downwardly along the outer wall thereof into the basin 400 where it is mixed with the drained wash solution flowing from the mass 102 of tightly wound rolls 101 through the conveyor slats 211 into the drip pan 380 and trough 390 to be transported to the basin 400 by the hose 398, the mixed wash solution of make-up solution 485 and drained solution being designated by numeral 486.

Also disposed within the basin 400 is a pump 490; an off-on switch 491 connected to a shaft 492 leading to a float 493 operates the solenoid valve 481. The pump 490 is supported by means of a shaft 492 on a base 495 and is of the sump type thereby to provide pumping action for the mixed wash solution 486 through the base 495 upwardly through a suitable fitting 496 and a hose 497, the hose 497 leading to a heater 500.

The heaters 500 are of the conventional gas burning type and are mounted by struts 501 to supporting columns 115. The heaters 500 include a body portion 502, a hood disposed thereabove 503 and a vent portion 504 for hot gases to pass therethrough. There is also provided a gas header 506 and a gas supply pipe 507 leading from the header 506 to a gas flow control device 508 in communication with the heater 500, a suitable fitting 509 connects the gas supply pipe 507 with the control 508.

The sectional mixing stations 420 may be of the same type as the mixing station 410 or may be of a simpler construction as illustrated, the sectional stations 420 consisting of basins 421 similar in all respects to basin 400 and including a supply platform 424 vertically spaced from the basin 421 and providing support for a solid additives supply 422 and a liquid additives supply 423, the supplies 422 and 423 being in communication with the basin 421. A feed screw shaft 425 similar in all respects to the feed screw shaft 465 and associated hardware is also provided in the sectional mixing stations 420 for feeding the solid additives from the supply 422 to the basin 421. As hereinbefore explained, the sectional mixing stations 420 may be of simpler construction than the first mixing station 410 due to the fact that little wash solution is lost in the later zones, whereas large quantities of make-up wash solution are continuously needed in the first station 410 to initially wet the rolls 101 in the first zone. Each of the sectional mixing stations are provided with solenoid valves as hereinbefore described, the valves being operatively responsive to the level of wash solution in the basins 421 for controlling the amount of solid additives, liquid additives and water introduced into the basin 421. Each of the stations 420 is provided with a pump as hereinbefore described to pump the wash solution to an associated heater 500, all as described above.

In operation, an operator designated by the numeral 515 receives the rolls of tightly wound cloth in slings 516 consisting of eight rolls 101 of tightly wound, multi-layer rolls of pervious cloth, the slings 516 being transported by a conveyor 517 to the operator 515. Each roll 101 may consist of 50 yard long continuous toweling of the type used in closed loop towel dispensing machines, each roll 101 weighing about 6 pounds when dry and absorbing about 250 percent of their own weight in wash solution, therefore to weigh about 20 pounds when saturated. The rolls 101 of toweling introduced into the crib 106 at the loading area 170 to form a randomly arranged mass 102 about 4 feet in height are dry and therefore absorb large quantities of wash solution from the cascade 376 of wash solution overflowing from the trough 245 in the first zone, the first zone being defined by the reciprocal path that the trough 245 most adjacent to the loading area 170 travels. Since the rolls 101 when introduced into the crib 106 absorb huge quantities of wash solution, the first mixing stage 410 operates more or less continuously to provide freshly prepared wash solution to the first trough 245.

The fresh wash solution 485 is prepared upon activation of the solenoid valve 481 by the introduction of water through the water supply pipe 480, the water being introduced simultaneously with the additives, the water flow is either on or off and is controlled by the switch 491, the water being introduced tangentially to the inner mixing tube 415 thereby to form therein a vortex of water. The level of water in the inner mixing tube 415 as previously explained is maintained by the height of the wash solution in the outer return tube 416 thereby to insure the formation of a vortex of water within the inner tube 415. Additives introduced into the inner mixing tube 415 by the activation of solenoid valves 448, 449 and the solenoid control (not shown) for the motor 470 mix with the water in the inner mixing tube 415 due to the vortex formed by the water and the mixing action provided by rotation of the stirrer 435, the mixing pins 436 disposed thereon and the baffles or mixing pins 437 disposed on the inner wall of the tube 415. The mixed wash solution 485 flows downwardly through the mixing tube 415 and into the outer return tube 416 and upwardly therethrough to overflow from the top edge thereof into the basin 400. In the basin 400 there is a mixture 486 of the freshly prepared wash solution 485 and the wash solution drained from the rolls 101 and returned to the basin 400 by the tube 398, operation of the mixing station 410 to provide a constant volume of wash solution to the first trough 245 and therefore to the cascade 376.

The wash solution may contain various fatty acid soaps for grease removal and non-ionic detergents or it may contain alkali such as sodium hydroxide which may be added to the wash solution in either liquid or solid form, additionally other enzyme materials may be added as the case requires. Germ control may be attained by the use of chlorozone or other germ control agents. pH control may also be effected by the use of various acids. It is also contemplated that various other additives known in the washing art, such as phosphates, other buffers, soaps, detergents and alkalies may be used. It is seen therefore that each cascade 376 may contain one or more additives depending on the type of

soil to be loosened. The heater 500 for the first zone supplies wash solution to the first trough 245 at a temperature of about 180° to about 200° F., the elevated temperature providing improved soaking action.

As the conveyor system 190 transports the mass 102 of rolls 101 therealong and through the crib 106, the reciprocating troughs 245 combine therewith to periodically apply the wash solution in the form of cascades 376 thereto. Continual drainage of the excess wash solution is provided by the open slat conveyor chain 215 thereby to allow the excess wash solution to continually drain therethrough and into the drip pan 380 thereby to prevent the stagnation of the wash solution. The excess wash solution applied in each zone is collected separately by the drip pan 380 due to the high ribs 382 which are positioned at the terminal ends of sheets 385, the sheets 385 being equal in length to each reciprocal path for each trough 245 thereby separately to maintain the wash solutions in each zone. The wash solution from each zone collected on the drip pan 380 flows therefrom into the collecting trough 390 and thereafter through the drain hoses 398 back into the basins 400 and 421 where it is again mixed with make-up wash solution 485 freshly prepared and recirculated by means of the pumps 490 upwardly through the flexible hoses 497 to be reheated in heaters 500 and introduced therefrom to the respective trough 245.

As the mass 102 of rolls 101 is transported by the conveyor system 190 through the crib 106, it passes through consecutive zones, the zones being formed by the reciprocal path of each and every trough 245. In each zone the relative movement provided by the conveyor chain 215 and the troughs 245 serves to periodically apply the wash solution in the form of a cascade 376 from the troughs 245 onto the surface of the rolls 101 of tightly wound pervious cloth.

Clearly, it is seen that after the initial contact with the wash solution, the amount of wash solution draining through the rolls 101 is essentially equal to the amount of wash solution added thereto and therefore, the sectional mixing stations 420 are not required to provide the large quantities of make-up wash solution 485 that the first mixing station 410 is required to produce. Thus, the sectional mixing stations 420 generally provide little if any make-up wash solution, but serve principally to recirculate the collected wash solution from each and every zone to the heater 500 associated with that zone and from the heater 500 to the associated trough 245, each of the troughs 245 moving along its own reciprocal path, the sum total of the lengths of the reciprocal paths equal to the length of the crib 106 from the loading area 170 to the discharge area 180.

In addition to the soil-loosening action provided by saturation with the wash solution, improved loosening action may be attained by means of thermal shock introduced to the mass 102 of rolls 101 by subjecting the rolls 101 sequentially to wash solutions at different temperatures. For instance, wash solution may be supplied to the mass 102 of tightly wound rolls 101 at an elevated temperature of from about 120° to about 200° F. and in an adjacent zone wash solution may be supplied to the mass 102 of tightly wound rolls 101 at a temperature of about 50° F. thereby to provide thermal shock to the mass 102 of tightly wound rolls 101 and thereby to further loosen soil therefrom.

An advantage of the present invention is in the ability to vary the loading capacity of the crib 106 and thereby the production capacity by adding or deleting sections, as most clearly shown in FIGS. 4 to 6. Assuming that each of the sections between the support columns 115 is about 10 feet in length, then FIG. 4 shows a crib of about 20 feet in effective length, FIG. 5 shows a crib of about 40 feet in effective length and FIG. 6 shows a crib of about 40 feet in effective length. The flexibility obtained by assembling the soil loosening apparatus 105 of the present invention in uniform lengths or sections is particularly important in a growing economy wherein a plant processing continuous towels is never burdened with over-sized equipment or machinery which becomes obsolete after one or two years when production demands have increased.

For an apparatus as shown in FIG. 4, the plant capacity is between 1,000 and 3,000 rolls per day. The apparatus could be loaded with up to 1,600 towels at one time, and these 1,600 towels would be expelled and washed during the 4 morning hours and during the four afternoon hours, the machine would again be loaded with 1,600 towels and stopped. During the evening hours troughs 245 could continue to reciprocate while the conveyor system was halted, thereby to continue applying the wash solution to the rolls of toweling and therefore all towels would be subjected to the wash solutions for 16 hours. As production demands increased, the same machine could be operated in shifts. To attain the rate of seven towels per minute, the machine could be operated for the four morning hours and loaded as the towels are discharged from the discharge area. By noon, 1,600 towels would have been processed and the machine would again be loaded and stopped. During the first 4 hours of the second shift, the loading and washing process would again be repeated. The towels loaded during the four morning hours would therefore be subjected to the wash solution for 8 hours and the towels loaded during the first 4 hours of the second shift would be subjected to the wash solution for 12 hours, the total capacity would then be 3,200 towels per day.

For the 40 foot apparatus shown in FIG. 5, a capacity of 3,200 is achieved. For the same rate of seven towels per minute, towels are loaded and washed for 8 hours, the conveyor being stopped during the night, but the wash solution being continually applied by the troughs. In this manner, all towels in the machine are subjected to the wash solution for 24 hours and in this manner the two shifts required to process 3,200 towels in the apparatus shown in FIG. 4, has been reduced to one shift in the apparatus in FIG. 5. If production demands again increase, the 40 foot machine can be operated for two shifts. For instance, towels can be loaded and washed during the first 8 hour shift producing 3,200 towels at seven towels per minute. This process can be repeated during the second shift and thereafter the conveyor be stopped during the third shift while the wash solution is continually applied to the towels. Therefore, one half of the towels processed are subjected to the wash solution for 8 hours and the other half for 16 hours.

Again, if production demands increase, the machine can be extended to six or eight sections of 10 feet each, for instance as shown in FIG. 6. The modular construction of all component parts makes such an expansion

feasible or conversely, on the other hand, if production capacity decreases, sections can be removed from the machine as easily as being added thereto. In each case however the rolls 101 are subjected to the wash solution for a time in excess of 8 hours, the minimum time required for effective soil-loosening action and in some cases the rolls 101 are subjected to the wash solution for up to 24 hours.

In a constructional example, the crib 106 contains stainless steel liners 143, the side walls 107 and the cross-ties 113 forming a chamber 10 feet wide by 4 feet high, the length of the crib 106 being variable as hereinbefore described, but conveniently being made in 10 feet long sections. The conveyor chain 215 consists of tubular slabs 12 feet long, the chain 215 being positioned out of contact with the wash solution. The I-beams 195 are pitched downwardly from the loading area 170 to the discharge area 180 to utilize gravity to decrease the torque on the drive motor. The side walls 171 of the loading area 170 are about 2 feet in length and 4 feet in height and are spaced apart about 10 feet. The troughs 245 are reciprocable along a path 10 feet in length to correspond to the 10 feet sections of the crib 106, each trough completes its reciprocal motion in approximately 1 minute to evenly distribute the cascade 376 of wash solution 375 onto the mass 102 of rolls 101 which is 4 feet high.

With regard to the first mixing station 410, the bottom of the inner mixing tube 415 is spaced about 3 inches from the bottom of the outer tube 416 and the top edge of the outer tube 416 is about 6 inches below the water inlet 480. For a residence time in the tube 415 of about 30 seconds for water entering the tube 415 at a rate of about 13 gallons per minute, the tube 415 is 4 feet 6 inches high. The solenoid-operated water-inlet valve 481 and all additive supplies are electrically interlocked for either a high-low or an on-off operation controlled by the float switch 491 in the first station 410.

While the above described soil-loosening apparatus 105 particularly illustrates four zones and four flooding troughs 245 therein, it is clear that the invention is intended to cover a machine of any number of zones, from one to whatever capacity is required, the operating principle being essentially the same for all. The important features of the invention being the V-shaped flooding troughs 245 used to assure an evenly distributed cascade 376 of wash solution 375 over the mass 102 of tightly wound rolls 101 all without the usual spray nozzle systems involving the problems of clogging and complicated pumping systems to provide the required static pressure for the spray nozzle. Additionally, the gravity movement of the wash solution 375 through the mass 102 of tightly wound rolls 101 greatly enhances its soil-loosening action to provide soil loosening not possible by total immersion in a liquid even if the liquid is mechanically agitated. Another feature of this invention is the continual draining of the wash solution 375 from the mass 102 of tightly wound rolls 101, the periodic application of the wash solution being sufficient to provide saturation of the tightly wound rolls 101 to the innermost layer thereof upon the exit of the rolls 101 from the last zone of the machine 105 into the discharge area 180.

It may be seen therefore that there has been provided apparatus and method for loosening soil from a mass 102 of randomly arranged, tightly wound, multi-layer rolls 101 of pervious cloth including a foraminous conveyor 215 for transporting the mass 102 of tightly wound rolls 101 through a crib 106 surrounding the conveyor 215 for retaining the mass 102 of tightly wound rolls 101 thereon, a supply mechanism 240 associated with the crib 106 and including a plurality of troughs 245 overlying the conveyor 215, the troughs 245 being operable to produce cascades 376 of wash solution 375 from the troughs 245 directed onto the conveyor 215 and the mass 102 of tightly wound rolls 101 supported thereby, the troughs 245 being respectively reciprocable along longitudinally aligned paths overlying the conveyor 215 thereby to form a plurality of zones, operation of the conveyor 215 serving to move the mass 102 of tightly wound rolls 101 from the loading port 170 to the discharge port 180 through the plurality of zones formed by the cascades 376 of wash solution 375, the conveyor 215 and the crib 106 being constructed and arranged for the continual draining of excess wash solution from the mass 102 of tightly wound rolls 101 on the conveyor 215 during the passage thereof from the loading port 170 to the discharge port 180, a drip pan 380 and collecting trough 390 associated with each zone for collecting excess wash solution draining from the mass 102 of tightly wound rolls 101 transported by the conveyor 215 through each of the zones and for recirculating to the associated one of the troughs 245 the excess wash solution so collected, means including the collecting basins 400 and 421 and the mixing stations 410 and 420 for adding make-up wash solution respectively to the drained wash solution from each zone in response to depletion of the drained wash solution from the respective zone to maintain substantially constant in volume the cascades 376 of the wash solution directed onto the conveyor 215 and the mass 102 of tightly wound rolls 101 supported thereby, a plurality of temperature controlled devices 500 for controlling the temperature of the plurality of cascades 376 of wash solution thereby to apply the wash solution in at least some of the zones at an elevated temperature of about 180° to about 200° F. with respect to the wash solution at about 50° F. in an adjacent one of the zones sequentially to subject the mass 102 of tightly wound rolls 101 to wash solutions at different temperatures to induce thermal shock in each of the tightly wound rolls 101, the application of the plurality of cascades 376 of wash solution to the mass 102 of tightly wound rolls 101 directing the transport thereof by the conveyor 215 through the zones serving to maintain the surfaces of the rolls 101 wet for a time sufficient to saturate each of the tightly wound rolls 101 to the innermost layer thereof upon exiting from the last of the zones, whereby substantially to loosen all of the soil disposed on and in the cloth forming the tightly wound rolls 101 during the transportation thereof through the crib 106 on the conveyor 215.

There has also been provided an apparatus for preparing wash solution 485 comprising an elongated inner cylinder 415 being open at both ends, an elongated outer cylinder 416 disposed about the inner cylinder 415 and spaced therefrom to provide an annulus therebetween, the outer cylinder 416 being closed

at the bottom end 417 thereof and being spaced at the bottom end 417 thereof from the bottom end of the inner cylinder 415, the outer cylinder 416 having the top edge thereof spaced below the top edge of the inner cylinder 415, a reservoir 400 for holding freshly prepared wash solution 485 disposed about the bottom 417 of the outer cylinder 416, the reservoir 400 being so positioned to receive freshly prepared wash solution 485 flowing from the outer cylinder 416, a stirrer 435 disposed in the inner cylinder 415 including a plurality of members 436 extending outwardly from the stirrer 435, a plurality of baffles 437 extending from the inner walls of the inner cylinder 415, the baffles 437 and the outwardly extending members 436 cooperating upon rotation of the stirrer 435 to provide a mixing action in the inner cylinder 415, a water supply pipe 480 for introducing water into the inner cylinder 415 tangentially to the inner wall thereof, the water supply pipe 480 being positioned below the top edge of the inner cylinder 415 and above the top edge of the outer cylinder 416, thereby to produce a vortex of water inside the inner cylinder 415, first control means 481 associated with the water supply pipe 480 for controlling the flow of water therethrough, an additive supply 440, 441 and 450 in communication with the inner cylinder 415, second control means including solenoid valves 448 and 449 associated with the additive supplies 440, 441 and 450 for controlling the amount of additives therefrom to the inner cylinder 415 for mixing with the vortex of water, a pump 490 for pumping wash solution 486 from the reservoir 400, and means including a float 493 responsive to the level of the wash solution 486 in the reservoir 400 for operating the first and second control means including solenoid valves 481, 448 and 449 to introduce water and additives to the inner cylinder 415, whereby the additives introduced into the inner cylinder 415 with the water are mixed with the vortex formed thereby and flow downwardly through the inner cylinder 415 into the outer cylinder 416 and upwardly through the annulus formed between the inner cylinder 415 and the outer cylinder 416 to flow from the outer cylinder 416 into the reservoir 400 to maintain constant the level of wash solution 486 in the reservoir 400 when the pump 490 is operative to pump wash solution 486 therefrom.

Upon discharge from the soil-loosening apparatus 105, the rolls 101 are transported by conveyor or by hand to an orbital washer 525, the orbital washer 525 being particularly illustrated in FIGS. 21 to 34.

The orbital washer of the present invention is related to a washer disclosed in my co-pending application, Ser. No. 746,012 filed on July 19, 1968, entitled CONTINUOUS WASHING METHOD AND APPARATUS, which was a division of my co-pending application Ser. No. 499,137, filed Oct. 21, 1965, entitled CONTINUOUS WASHING METHOD AND APPARATUS, now U.S. Pat. No. 3,439,365, the disclosure therein being incorporated herein by reference. The washing machine therein disclosed is entirely effective to disassociate soil from the cloth fabric articles; however, difficulties are encountered in maintaining the bearings supporting the conveyor lubricated due to the fact that the bearings are immersed in the wash solution. The novel method and apparatus of the present invention entirely eliminates the above-

described problem by mounting the shafts supporting the conveyor on bearings located at a point removed from the wash solution, thereby preventing the wash solution from contacting and removing the lubrication therefrom. An additional and entirely novel aspect of the present invention is the provision of mechanism for imparting orbital movement to an entire section of the tank walls, the apparatus supporting the movable walls including bearings also positioned external to the tank and therefore maintained out of contact with the wash solution contained therein.

The washer 525 includes a tank 530 for holding a wash solution, the tank 530 including two spaced-apart stationary side walls 531, an upper edge of each of the stationary side walls 531 being formed into an outwardly extending flange 532, the stationary side walls 531 being generally U-shaped. The tank 530 further includes a bottom wall 533 interconnecting the side walls 531 and two spaced-apart upstanding end walls 534, all for containing therein a wash solution 535. At the bottom of the tank 530 fixed to the bottom wall 533 are a pair of longitudinally extending laterally spaced-apart tracks 538, the tracks 538 being for a purpose hereinafter to be explained.

The tank 530 also includes two movable side walls 541, each movable side wall 541 including at the upper edge thereof a stiffening angle 542, the side walls 541 further including two spaced-apart crank shaft apertures 543 and a plurality of conveyor support apertures 544, corresponding apertures 543 and 544 in each wall 541 being aligned and in registry to permit the passage therethrough of a horizontally positioned shaft. Affixed to the flange 532 on the stationary side wall 531 is a wall seal 546, the wall seal 546 being suitably secured to the flange 532 by means of a plurality of spaced-apart washers 547, headed bolts 548 and fastening nuts 549.

Fixed to the outer side of each of the movable side walls 541 of the tank 530 is a support frame 555, the support frame 555 being generally channel-shaped and including two vertically spaced-apart legs 556 interconnected by a web portion 557, the legs 556 each have on the ends thereof and integral therewith attachment flanges 558 connected to the tank walls 541 by suitable nuts and bolts 559. The support frames 555 have provided therein two crank shaft apertures 563 in registry with the crank shaft apertures 543 in the movable side walls 541 and a plurality of conveyor support apertures 564, each respectively in registry with a corresponding conveyor support aperture 544 in the movable tank walls 541.

As illustrated, there are provided two crank shafts 570 and 570a, each of the crank shafts 570 and 570a including an eccentric surface 571 and a bearing surface 572, rotation of the shafts 570 and 570a providing orbital movement of one-eighth inch diameter. Disposed about each of the crank shafts 570 and 570a on both sides of the movable walls 541 is a crank shaft seal 576, the seals 576 being circular in shape and each being suitably retained against the movable side walls 541 by means of a circular flange 577, the flanges 577 having an attachment portion 578 and an off-set portion 579, the seals 576 being held between the off-set portion 579 of the flange 577 and the wall 541 by suitable nuts and bolts 580.

As may be seen, the crank shafts 570 and 570a extend outwardly through the movable walls 541 and are supported exterior thereto by pedestals 585. The pedestals 585 include a pillow block 586 inside of which are positioned bearing shoes 587 and bearing sleeves 588, the bearing sleeves 588 are suitably fixed to the crank shafts 570 and 570a by means of set screws 589. Retained within the ball recess formed by the bearing shoes 587 and the bearing sleeves 588 are ball bearings 590. Thus, the crank shafts 570 and 570a have their bearing surfaces 572 rotatably mounted within the pillow blocks 586, all exterior to the tank 530. The eccentric surfaces 571 of the crank shafts 570 and 570a are rotatably mounted within bearing assemblies 595 formed of angle plates 596 having a vertical portion and a horizontal portion, the horizontal portion of the angle plates 596 carrying on the end sides thereof outer races 597. Surrounding the eccentric surfaces 571 of the crank shafts 570 and 570a are a pair of inner races 598, one of the inner races 598 being positioned internally of the support frames 555 and the other of the inner races 598 being positioned external to the support frames 555, positioned between the inner races 598 and the outer races 597 are ball bearings 600 thereby to rotatably support the crank shafts 570 and 570a within the support frames 555 and apertures 563 therein.

Disposed on the bearing surface 572 of the crank shaft 570 outwardly of the pedestals 585 are two drive sprockets 605 and 605a, the drive sprockets 605 and 605a being fixedly mounted onto the bearing surface 572 by set screws 606. Similarly mounted on crank shaft 570a is an idler sprocket 608, the idler sprocket 608 also being mounted on the bearing surface 572 of the crank shaft 570a by means of a set screw (not shown), the crank shaft 570a being suitably journaled at the other end thereof in like assembly denoted as 602, as seen in the upper portion of FIG. 22. Interconnecting the drive sprocket 605 and the idler sprocket 606 is an endless chain 607. A motor 610 with a drive shaft 611 and a drive sprocket 612 fixedly connected thereto provides rotation of the crank shafts 570 and 570a, interconnecting the drive sprocket 612 with the drive sprocket 605 is a drive chain 613, rotation of the drive chain by activation of the motor 610 providing rotation of the crank shafts 570 and 570a by means of the interconnecting endless chain 607 therebetween and hence orbital movement of the movable walls 541.

Toweling is transported through the orbital washer 525 by a conveyor supported by a festoon of rollers 620, the festoon of rollers 620 comprising two series of rollers, the series being arranged generally horizontal to and vertically spaced apart one from the other. The festoon 620 is comprised of a plurality of rollers 655 each of the rollers 655 is identical and therefore only one will be explained in detail. As shown in FIG. 23, each roller 655 is supported by a hollow shaft 625, the shaft being rotatably journaled in pivot block 626 as shown in the top of FIG. 22 and carrying on the other end thereof a sprocket 627 fixedly attached to the shaft 625 by a set screw 628. Each of the shafts 625 extends through two aligned holes or apertures 544 in the movable side walls 541; sealing between the side walls 541 and the shafts 625 being provided by a plurality of circular shaft seals 536 fixedly mounted to the movable

side walls 541 by a corresponding number of circular flanges 637, each of the flanges 637 having an attachment portion 638 and an off-set portion 639. As seen from the Figures, each of the seals 636 is held 5 between the off-set portion 639 of the associated flange 637 and the associated side wall 541 of the tank 530 by means of appropriate nuts and bolts 640. The shafts 625 are further mounted to each of the support frames 655 by means of an external mounting block 645 fixedly mounted to the support frames 555 by means of 10 suitable nuts and bolts 646; the hollow shafts 625 are provided with the usual and suitable bearings 647.

Each of the hollow shafts 625 provides support for a 15 plurality of hubs 650, the hubs 650 being generally cylindrical in shape and having on one end thereof a tongue 651 and having on the other end thereof a groove 652, the tongue 651 being adapted to fit within an associated groove 652 of the adjacent hub thereby 20 to provide interlocking between adjacent hubs 650, the outermost hubs 650 being fixedly secured to the associated shaft 625 thereby to cause rotation of all the hubs therewith. Each of the hubs 650 provides support 25 for the above-mentioned rollers 655, each of the rollers 655 including a circular wheel rim 656 connected to the associated hub 650 by means of a plurality of radially extending spokes 657, the wheel rim 656 carries on the outer surface thereof extending outwardly therefrom a plurality of studs 658, all for a purpose 30 hereinafter disclosed.

Rotation of the shafts 625 and hence the hubs 650 and the rollers 655 is provided by means of a motor such as the motor 610 or another drive motor (not shown) suitably connected to drive an endless chain 660 interconnecting each of the sprockets 627 fixedly attached to the end of shafts 625, the endless chain 660 including links 661 and rivets 662 interconnecting the links 661, the links 661 being adapted to fit over the distal ends of the sprockets 627, thereby rotation of the chain 660 causing rotation of the sprockets 627 and hence rotation of the rollers 655 about the central axis of the shafts 625, all to provide drive mechanism for a conveyor 670.

45 There is further provided a plurality of idler rollers 655b mounted on two idler shafts 625b journaled in the stationary wall section 531 of the tank 530 positioned near the top thereof and a plurality of idler rollers 655a supported by two idler shafts 625a, the shafts 625a being supported at a distance from the tank 530, the idler rollers 655a and 655b serving to provide the 50 endless chain 660 with a return flight 660a. It is noted that the two series of rollers 655 in the festoon 620 are alternately placed thereby to facilitate the 55 passage of the endless chain over and around one of the rollers and under and around the next adjacent roller and so on through the tank 530 to provide a tortuous path for the conveyor 670 as hereinafter explained.

There is further provided the conveyor 670 for transporting 60 flat work in the form of a plurality of lanes of pervious cloth 675 arranged side-by-side through the tank 530, the flat work 675 being provided from a plurality of tightly wound rolls 676 of toweling such as that which exits from the soil-loosening apparatus 105, the rolls 676 being positioned side-by-side in a support trough 677 fixedly connected to the left-hand end wall 534, as viewed in FIG. 25, by struts 678 and extending 65

the width of the washer 525. The conveyor 570 includes a lower endless mesh belt 680 constructed of a corrosion-resistant material such as stainless steel or suitable synthetic plastic material in the form of a balanced mesh including links each formed of a longitudinal portion 681, the longitudinal portion 681 extending in a direction parallel to the longer dimension of the tank 530 and a transverse portion 682, the transverse portion 682 being joined to the longitudinal portion 681 and extending generally normal thereto, the mesh further including a plurality of zig-zag loops 683 connected to the longitudinal portion 681, the loops 683 having a plurality of alternate colinear apexes 684, the longitudinal portions 681 of each link being joined together by a suitable weldment 685. The conveyor 670 further includes an upper endless mesh belt 690, the upper belt 690 being formed of a balanced mesh similar to the lower belt 680 and constructed of the same corrosion-resistant material. As seen in FIG. 26, the conveyor 670 has at one end a loading portion 694 of the lower belt 680 onto which the flat work 675 is introduced, the flat work 675 being transported by the lower belt 680 to a point where the upper belt 690 forms therewith a laminar portion 695 of the conveyor 670. The laminar portion 695 as specifically shown in FIGS. 29 and 30, securely holds the flat work 675 between the upper belt 690 and the lower belt 680, the construction of the balanced mesh providing for displacement of the flat work 675 between the full-line position and the dotted-line positions as shown in FIG. 30 during cycloidal movement of the flat work 675 as it is transported through the wash solution 535 in the tank 530, the cycloidal motion being imparted thereto by the combination of the forward movement along the conveyor 670 and the orbital motion due to the tank walls 541 and rotation of the shafts 570 and 570a. As seen, the laminar portion 695 of the conveyor 670 transports the flat work 675 over, around and under the rollers 655 which form the two alternate series of the festoon 620 thereby to form the tortuous path along which the flat work 675 is transported through the tank 530. The flat work 675 is introduced onto the loading portion 694 of the lower belt 680 and transported thereby to the point where the upper belt 690 joins therewith to form the laminar portion 695 thereof, the laminar portion 695 then being transported, as hereinbefore stated, over the rollers 655 toward the discharge end of the tank 530. As viewed in FIG. 25 on the right-hand side thereof and in FIG. 27, the flat work 675 is transported to a point where the laminar portion 695 of the conveyor 670 ceases and a discharge portion 696 of the lower belt 680 transports the flat work 675 from the orbital washer 525. At the termination point of the laminar portion 695 of the conveyor 670, the upper belt 690 forms a horizontal return flight 697 while the lower belt 680 forms the discharge portion 696 and thereafter forms into the return flight 698 of the lower belt 680, the return flight 698 of the lower belt 690 returning adjacent the bottom 533 of the tank 530 on the tracks 538 provided therefor.

Operation of the orbital washer 525 is as follows, the crank shafts 570 and 570a are rotated upon activation of the motor 610 by the drive chain 613 and the chain 607 interconnecting the drive sprocket 605 and the idler sprocket 608 connected to the crank shafts 570

and 570a respectively. Upon rotation of the crank shaft 570 and 570a orbital motion is provided due to the eccentric portions 571 of the crank shafts 570 and 570a, this orbital motion is imparted to the movable walls 541 of the tank 530 as hereinbefore described by the rotatable mounting of the crank shafts 570 and 570a in the support frames 557 which are fixedly mounted to the movable wall 541. As the hollow shafts 625 supporting the rollers 655 which in turn support the conveyor 670 are connected to the movable wall 541 by means of the support frames 557 and the bearings 657, orbital movement of the crank shafts 570 and 570a imparts corresponding orbital movement to the movable walls 541 and thereby to the hollow shafts 625 and to the conveyor 670. During movement of the conveyor 670 through the wash solution 535, the conveyor has a longitudinal vector as well as an angular vector thereby to impart to the flat work 675 carried thereby a cycloidal motion with respect to the wash solution 535 contained in the tank 530 thereby to disassociate soil from the flat work 675 comprised of multiple lanes of pervious cloth arranged side-by-side, the washed flatwork being designated 675a.

The novel arrangement of the orbital washer 525 provides cycloidal motion to the flat work 675 transported therethrough by rotatable shafts 570, 570a and 625 mounted exterior to the washer 525 thereby to prevent contact of the wash solution 535 with the bearings rotatably supporting the shafts. As may be appreciated, the wash solution 535 is designed to cut grease, dirt and oils and is effective against oils which may be used for lubrication and, therefore, contact of the wash solution 535 with the bearings used to mount the crank shafts 570 and 570a and the hollow shaft 625 would result in removal of lubrication from the bearings thereby to burn the bearings and destroy the same.

The novel arrangement hereinbefore disclosed provides for the first time an orbital washer in which the rotating shafts are mounted on bearings exterior to the tank, thereby cutting the maintenance problems heretofore incurred with orbital washers of this type. There is further provided herein a novel movable wall in which an entire section of the tank moves with rotation of the crank shafts, there being no similar apparatus heretofore provided.

It may be seen therefore that there has been provided an apparatus 525 for washing soiled articles 675 comprising a tank 530 including movable side walls 541, a conveyor 670 for transporting the soiled articles 675 through the tank 530, a plurality of shafts 625 extending through the movable side walls 541 of the tank 530 for supporting the conveyor 670, the shafts 625 being mounted on bearings 647 outside of the tank 530, a plurality of seals 636 between the shafts 625 and the movable side walls 541 of the tank 530 to prevent contact of the bearings 647 with the wash solution 535, thereby to prevent the wash solution 535 from removing lubrication from the bearings 647, drive mechanism including motor 610 for imparting orbital movement to the movable side walls 541 and thereby to the shafts 625, whereby rotation of the shafts 625 and the orbital movement imparted thereto by the movable side walls 541 impart cycloidal motion to the articles 675 transported by the conveyor 670 with respect to the wash

solution 535 in the tank 530 to disassociate soil from the articles 675.

The rinser of the present invention is related to my co-pending application Ser. No. 746,157, filed on July 19, 1968, entitled CONTINUOUS WASHING METHOD AND APPARATUS which was a division of my co-pending application Ser. No. 499,137, filed Oct. 21, 1965, entitled CONTINUOUS WASHING METHOD AND APPARATUS, now U.S. Pat. No. 3,439,365, the disclosure therein being incorporated herein by reference. The rinser therein disclosed is entirely effective to rinse wash solution from fabric articles containing the same; however, difficulties are encountered due to the formation of puddles of rinse liquid and wash solution on the fabric articles thereby decreasing the amount of rinse mist being forced therethrough. The novel method and apparatus of the present invention eliminates the above described problem by directing the mist through the articles in a path normal to the articles, thereby to prevent the formation of puddles thereon.

The washed flat work 675a which exits from the orbital washer 525 along the discharge portion 696 of the lower belt 670 is fed to a syphon-surge rinser 710. The rinser 710 includes a pair of spaced-apart U-shaped frame members 715, each of the frame members 715 having two spaced-apart legs 716 interconnected by a bight 717, the frame members 715 are interconnected by cross-ties 718 thereby to provide a frame for the rinser 710 which is stationary and stable. The U-shaped frames 715 further includes two lateral supports 721 generally parallel to the bights 717 and downwardly spaced therefrom, the support 721 extending between the legs 716, lateral supports 721a and 721b extend horizontally outwardly from the legs 716 and are spaced above support 721. Four vertical supports 722 extend upwardly from each support 721 and are adjacent to the legs 716 of the U-shaped frames 715 for a purpose to be hereinafter disclosed. There is further provided vertical supports 722a also extending upwardly and downwardly from each support 721 and vertical supports 722b extending upwardly from each bight 717. All of the supports hereinbefore described are provided as support for the drive mechanism and conveyor hereinafter described.

Journalled to the right-hand U-shaped frame 715, as viewed in FIG. 34, are a plurality of hollow shafts 725, the shafts 725 extending perpendicular to the plane defined by the frames 715 being journaled in pivot blocks 726, the shafts 725 carrying on the other end thereof sprockets 727, the shafts 725 being supported by the above-mentioned supports 721, 721a, 721b, 722, 722a and 722b. Adjacent to the U-shaped frames 715 and disposed about the shafts 725 are spacers 728, the spacers 728 being in the form of tubes for a purpose hereinafter to be explained. Positioned on the shafts 725 intermediate the spacers 728 are a plurality of hubs 730, the hubs 730 being similarly constructed to the hubs 650 in the orbital washer 525 and also provided with tongues and grooves (not shown), each hub 730 supporting therearound a roller 735 formed of a wheel rim 736 and interconnected to the hub by spokes 737 extending radially from the hubs 730 to the wheel rim 736. As may be seen, the combination of the spacer tubes 728 and the hubs 730 provide relatively little room for lateral movement of the rollers 735.

There is further provided an upper endless chain 740 and a lower endless chain 741, the upper endless chain 740 moving in a counter-clockwise direction about sprockets 727h, 727i, 727j and 727k. The lower chain 741 moves in a clockwise direction about sprockets 727a to 727g as shown in the figure, there further being provided a pair of idler wheels 745 suspended on a pair of spaced-apart generally parallel shafts 746, the idler wheels 745 serving to maintain the lower endless chain 741 taut. Movement of the lower endless chain 741 is provided by the motor means 750 mounted on a plate 751 and having extending therefrom a drive shaft 752 fixedly connected to a drive sprocket 753. The drive sprocket 753 is connected by an endless chain 754 to an outer sprocket 755 fixedly connected to a rotatable shaft 756, the shaft 756 further including an inner sprocket 757. As may be seen, activation of the motor 750 produces rotation of the drive shaft 752 thereof, which in turn drives the endless chain 754 in a counter-clockwise direction, thereby to rotate the outer sprockets 755 and the shaft 756 also in a counter-clockwise direction. The lower endless chain 741 passes over the sprockets 727a, 727b, 727c and 727d, it thereafter passes under the inner sprocket 757 and thereafter upwardly over sprockets 727e, 727f and 727g, thereby counter-clockwise rotation of the sprocket 757 provides clockwise rotation of the lower endless chain 741 and thereby clockwise rotation of the sprockets 727 and hence the rollers 735 supported by the shafts 725 supporting the above-mentioned sprockets 727a-g.

The counter-clockwise rotation of the upper endless chain 740 is provided by a drive chain 760 between a driven sprocket 761 and a driving sprocket 762 mounted on the shaft 756 driven by the motor 750. There is also provided an idler sprocket 765, as shown. The upper endless chain 740 passes underneath the sprockets 727h and 727i and over the sprockets 727j and 727k; after passing over the sprocket 727j, the chain 740 passes under the outer sprocket 765; therefore, clockwise rotation of the shaft 766 carrying the outer sprocket 765 and inner sprocket 767 thereon provides counter-clockwise rotation of the chain 740 and thereby the sprockets 727h-k, the associated shafts 725 and the rollers 735 carried thereby. From the above, it is seen that there is provided an upper endless chain 740 rotating in the counter-clockwise direction and a lower endless chain 741 rotating in the clockwise direction.

As hereinbefore explained, the upper endless chain 740 induces counter-clockwise rotation of the sprockets 727h through 727k and thereby counter-clockwise rotation of the corresponding shafts 725 while the lower endless chain 741 provides clockwise rotation of the sprockets 727a through 727g and thereby clockwise rotation of the corresponding shafts 725. The respective shafts 725 each support a plurality of rollers 735, the rollers 735 rotating in the same direction as the associated shaft.

As may be best seen in FIG. 35, there is provided a conveyor 770, the conveyor 770 including a lower endless mesh belt 780, the belt 780 being of the four-drinier type wire mesh cloth and constructed of a corrosion-resistant material such as stainless steel or an appropriate synthetic material, and an upper endless mesh belt 790, the upper belt likewise being con-

structed of a corrosion-resistant material. The lower mesh belt 780 and the upper mesh belt 790 both are supported by and transported by the rollers 735, the lower belt 780 and the upper belt 790 being positioned to provide a laminar portion 795 for transporting the flat work 675a therebetween. The upper endless belt 790 and the lower endless belt 780 therefore combine to transport the flat work 675a along a predetermined horizontally disposed path. It should be here noted that the belts 780 and 790 are not the same construction as the mesh belts forming the conveyor 670 and are sufficiently wide to provide transportation for flat work 675a composed of ten lanes of continuous sheets of toweling arranged in a side-by-side relationship similar to the conveyor 670 transporting the flat work 675 through the orbital washer 525.

The laminar portion 795 of the conveyor 770 containing the lower endless belt 780, the upper endless belt 790 and the flat work 675a disposed therebetween passes along a horizontal path adjacent to a plurality of rinsing units 800. The rinsing units 800 are identical in construction, and therefore only one will be described for the sake of brevity and simplicity. There is shown for the sake of example only, three rinsing units 800, the units being distinguished where necessary by the addition of a reference letter to the appropriate reference numeral. The rinsing units 800 each include a steam manifold 805, the manifold 805 being generally U-shaped in cross-section and including two upstanding spaced-apart side walls 806 interconnected by a transversely extending top wall 807, the side walls 806 carry on the ends thereof and integral therewith outwardly extending attachment flanges 808, the attachment flanges 808 being fixedly and suitably secured to a horizontally disposed bottom wall 809, the bottom wall 808 having a plurality of spaced-apart apertures 810 therein. The rinsing units 800 are each disposed with the longer dimension thereof transverse to the path of the laminar portion 795 of the conveyor 770 and as may be seen in FIG. 36, each of the steam manifolds 805 is inclined from the right-hand side of the figure to the left-hand side of the figure, thereby to provide a larger vertical extent of the side walls 806 at the left than at the right and a decreasing column as steam travels from the left to the right, thereby to maintain the even pressure thereof in the inlets 849.

Disposed below the bottom wall 809 of each of the steam manifolds 805 is a mixing chamber 815, each of the mixing chambers 815 being identical and including two spaced-apart diagonally inwardly slanting side walls 816, the side walls 816 having at the upper ends thereof and integral therewith outwardly extending attachment flanges 818, the attachment flanges 818 being suitably secured to the bottom wall 809 of the steam manifold 805. As may be seen, the side walls 816 of each of the mixing chambers 815 extend downwardly to a point 823 where they depend from that point in straight vertical portions 824, the straight vertical portions 824 are positioned to form a right angle with the laminar portion 795 of the conveyor 770, the two straight vertical portions 824 of the side walls 816 form a nozzle 825. The steam manifolds 805 and mixing chambers 815 are each further provided with a front wall 827 and a rear wall 828, the attachment flanges 808 and 818 being suitably secured to

the respective bottom wall 809 of the steam manifold 805 by nuts and bolts 829.

Outwardly disposed of each of the nozzles 825 and suitably attached thereto are two generally L-shaped shoes 835 for a purpose hereinafter explained, the shoes 835 each including a straight vertical portion 836 suitably attached to the straight vertical portions 824 forming the nozzle 825 and horizontally outwardly extending portions 837, the portions 837 being generally parallel to the laminar portions 795 of the conveyor 770. At the distal ends of the horizontal portions 837 of the shoes 835 and integral therewith are upturned ends or guides 838, the shoes 835 including the ends 838 principally being provided to prevent snagging of the mesh belts 780 and 790.

Disposed within the mixing chamber 815 at spaced-apart points therealong are a plurality of spacers 845, the spacers 845 extending generally parallel with the direction of travel of the conveyor 770, that is generally transverse to the longer dimension of the mixing chamber 815. Each two spacers 845 provides contact for a partition 846, there being a plurality of partitions 846 each extending the width of the mixing chamber 815, each partition being formed of two side walls 847 extending diagonally inwardly and upwardly from the spacers 845, the side walls 847 being joined by a horizontally extending top wall 849, each top wall 849 being provided with an aperture 850 therein, each of the apertures 850 being in registry with a corresponding aperture 810 in the bottom walls 809 of the steam manifolds 805. The partitions 846 providing for individual nozzle shapes for the rinsing unit 800, it being noted that the spacers 845 are kept very narrow because no rinsing action is possible along the part of the flat work 675a directly underneath the spacers 845.

Each mixing chamber 815 contains therein a weir 855 to provide a water storage section, the weir 855 includes a straight portion 856 extending downwardly and abutting one of the straight vertical portions 824 forming the nozzle 825, the weir 855 further including an upwardly and outwardly diagonally inclined portion 857 integral with and extending from the straight portion 856, the portion 857 also to provide strength. Suitably connected to the lower portion of each of the mixing chambers 815 is a water manifold 860 to provide water to the chamber defined by the weir 855 and the associated wall 816, the water manifold 860 including an elongated housing 861 extending essentially along the entire length of the mixing chamber 815, the housing 861 including therein a central bore 862, the bore 862 extending from one end of the manifold housing 861 up to but not through the outer end. At spaced-apart points, along the water manifold 860, there are provided a plurality of inlet bores 863, the inlet bores 863 being positioned generally normal to the central bore 862 and providing communication between the central bore 862 of the water manifold 860 with the chamber defined by the weir 855 and the wall 816 of the mixing chamber 815, it being noted that each of the inlet bores 863 aligned with one of the plurality of apertures 864 in the respective side wall 816 thereby to provide the hereinbefore mentioned communication. Each of the water manifolds 860 is further provided with rinse liquid supply pipes 865a-c leading from a rinse liquid supply to the associated manifold 860, there is

also provided an inlet pipe 865 leading to pipe 865d of the unit 800d and including therein a valve 867 having a control stem 868. As seen, the rinsing units 800a-c are positioned from left to right in the direction of travel of the flat work 675a, the rinse liquid, in the preferred embodiment water, enters rinsing unit 800d and from there as hereinafter explained to unit 800c to provide a countercurrent flow of the rinse liquid and the flat work 675a, as hereinafter described.

The rinsing units 800 are also provided with a steam header 870, the steam header 870 consisting of a horizontally disposed steam supply pipe 875 leading to a valve 877 having thereon a control stem 878 for controlling the amount of steam admitted to the header 870 from the supply pipe 875. Downwardly depending from the header 870 are a plurality of vertical header sections 870a, 870b and 870c, the vertical sections being suitably connected to each of the steam manifolds 805 by a fitting 879 disposed in the front wall 827 of each of the rinsing units 800. It should be noted that while each steam manifold 805 receives an individual steam header section 870a-c, only the last mixing chamber 815c receives the inlet water from the supply pipe 865.

Adjacent the conveyor 770 and disposed therebelow are a plurality of collecting vessels 880, there being a collecting vessel 880 for each and every rinsing unit 800. The collecting vessels 880 are identical in construction and therefore only one will be described for the sake of brevity, each collecting vessel 880 includes a pair of opposed inwardly slanting side walls 881 connected at the bottom thereof to form a heart-shaped unit in cross section. The side walls 881 curve inwardly at the top thereto to form an arcuate portion 882 and therefrom to form inwardly turned flanges 883, the flanges 883 having a straight portion 884 generally parallel to the conveyor 770 and having a downwardly turned portion 885, the downwardly turned portion 885 being integral with the flat portions 884. The collecting vessels 880 are each provided with a front wall 888 and a back wall 889. The opening formed between the opposed downwardly turned portions 885 of the flanges 883 is in registry with the nozzle 825 of the associated rinsing unit 800. Extending outwardly from the front wall 888 of the collecting vessel 880 is an exit pipe 890 suitably secured to the front wall 888 by a fitting 891. As noted in FIG. 35, each exit pipe 890 from one of the collecting vessels 880a, 880b, 880c, leads from the collecting vessel to a pump 895 which pumps the fluid from the exit pipe 890 through the next-adjacent inlet pipe 865 leading to an associated manifold 860. As seen in the figure, as the flat work 675a is transported by the laminar portion 795 of the conveyor 770 past the rinsing units 800a, 800b, 800c, the fluid from the rinsing unit is collected in the associated collecting vessel 880 and drained therefrom through the exit pipes 890a, 890b, 890c through the associated pumps 895a, 895b or 895c and pumped therefrom into the next associated water manifold 860b or 860a, thereby to provide counter-current flow of the rinse fluid to the movement of the flat work 675a.

In operation, a rinse liquid such as water is introduced to the water manifold 860d by means of the water supply pipe 865, the amount of water being introduced is controlled by the valve 867. Water flowing

into the manifold 860c enters the mixing unit 815c by means of the plurality of spaced-apart inlet bores 863 to form a water reservoir behind the weir 855. The water behind the weir 855 increases to a level where it overflows from the diagonally inwardly turned portion 857 of the weir 855. Concurrently with the introduction of the water into the pipe 856, there is provided the introduction of steam through the steam supply pipe 875 to the steam header 870, the amount of steam being introduced therethrough being controlled by the valve 877. Steam from the header 870 enters the header supply pipes 870a, 870b and 870c and is introduced thereby into the associated steam manifold 805a, 805b and 805c. The steam exits from the manifold 805 through the aligned apertures 810 in the bottom plate 809 and 850 in the top wall 849 and enters the mixing unit 815. The steam entering the mixing unit contacts the water overflowing the weir 855 thereby to form a mist, the mist being forcefully expelled due to the pressure of the steam contained in the mixing unit 815 through the nozzle 825, the nozzle 825 being formed at right angles to the conveyor 770 thereby to direct the mist of the steam and the water along a path at right angles to the flat work 675a being transported thereby.

An important feature of this invention is the prevention of the formation of puddles of rinse liquid and wash solution on the surface of the flat work 675a by positioning the nozzle 825 at right angles to the path of the flat work 675 and contacting the top belt 790 with the nozzle walls 824 thereby to prevent the formation of puddles thereon and to maintain constant the amount of mist being forced therethrough. The formation of puddles on the flat work 675a is highly undesirable because it decreases the amount of mist of rinse liquid and steam being forced through the flat work 675a and therefore decreases the rinsing action thereto.

The effluent of the wash solution and the mist drains into the associated collecting vessels, 880, in the initial case vessel 880c, it being understood that a sequential operation is taken for purposes of explanation, but all operations occur simultaneously during actual use. As the effluent drains into collecting vessel 880c, it is transported through this collecting vessel into the exit pipe 890c and therealong into the associated pump 895c wherein it is pumped upwardly into the manifold 860b of the rinse unit 800b, thereby to provide a counter-current flow of the effluent from one collecting vessel to the next associated rinsing unit to conserve the amount of rinse liquids used by the process. The effluent from the rinsing unit 800c is introduced into the manifold 860b and distributed as hereinbefore described into the mixing chamber 815b to be concurrently mixed with the steam introduced by the header 870b. As the effluent overflows the associated weir 855b to form therein a mist, the mist is forcefully expelled through the nozzle 825b which is positioned at right angles with the flat work 675a being transported thereby. It is here noted that the upturned ends 838 of the shoes 835 insure that no snagging of the wire mesh conveyor belt 790 occurs. Likewise, the downwardly turned portions 885 of the inwardly turned flanges 883 insure that the mesh of the lower belt 780 is also not snagged.

The effluent of the wash solution and the mist generated by rinsing unit 800b is collected in the associated collecting vessel 880b and transported therefrom through the exit pipe 890b to the associated pump 895b, therefrom it is pumped to the manifold 860a of the next associated rinsing unit 800a. The hereinbefore described process is repeated in the rinsing unit 800a, the effluent therefrom being collected in the associated collecting vessel 880a and drained therefrom through the exit pipe 890a. The associated pump 895a disposed of the collected effluent from the collecting vessel 880a via an exit pipe 896 to a waste disposal (not shown). It is noted that the flat work 675a transported from the orbital washer 525 contains upon the introduction to the rinsing unit 710 a considerable amount of wash solution 535. However, the flat work 675b exiting from the rinser 710 contains little if any wash solution, the rinsed state being denoted as 675b.

It may be seen therefore that there has been provided apparatus and method for rinsing wash solution from fabric articles including a rinsing unit 800 having a pressure chamber 805 and 815 for generating a mist of a gas and a rinse liquid, a rinse conveyor 770 for transporting the articles along a predetermined path adjacent to the rinsing unit 800, a nozzle 825 for the rinsing unit 800 including two spaced-apart walls 824 defining therebetween a passage through which the mist is forcibly expelled from the pressure chamber 805 and 815 and through the articles on the conveyor 770, a portion 824 of the walls 816 adjacent to the exit end of the nozzle 825 being disposed substantially normal to the predetermined path formed by the conveyor 770 to prevent puddles of the rinse liquid and the wash solution from forming on the associated article and thus decreasing the quantity of mist forced therethrough, and a collecting vessel 880 disposed adjacent to the rinse conveyor 770 in position to receive the mist and wash solution carried thereby passing through the articles, whereby to rinse the wash solution from the articles.

Upon exiting from the rinser 710, the flat work 675b is subjected to a sour spray applicator 900. The sour spray applicator 900 applies thereto a bleach spray after which the flat work 675b is deposited upon a time delay conveyor 905.

The time delay conveyor 905 which provides time for the bleach to penetrate the perivous cloth includes drive sprockets 907 rotatably mounted on drive shafts 908, the conveyor 905 further including an upper endless belt 910 and a lower endless belt 915. A plurality of idler sprockets 917 mounted on idler shaft 918 are provided to maintain the belts 910 and 915 taut. The time delay conveyor 905 is adapted in the length thereof and the speed of rotation thereof to provide a specific amount of time for the bleach applied by the bleach spray applicator 900 to become effective.

As the flat work 675b exits from the time delay conveyor 905, it is deposited upon another conveyor 770a which leads it to a rinser 710a, the rinser 710a including a rinsing unit 800d a conveyor 770a and a collecting vessel 880d, all identical in detail to one of the particular units as hereinbefore described. As the flat work 675b is transported past the associated nozzle of the rinse unit 800d a mist of the water and steam is force-

fully directed therethrough and the associated collecting vessel 880d receives the effluent therefrom. As the flat work 675b exits from the fourth-stage rinser 710a, it is subjected to an additional sour spray applicator 900a which applies thereto a sour, the flat work 675c so designated after the application of the sour thereto being directed to an extractor 925.

There is hereinafter disclosed an extractor system which for the first time provides extracting apparatus for the simultaneous extraction of ten lanes of cloth arranged in side-by-side relationship without the requirement of supporting the extracting equipment at points intermediate the length thereof and which for the first time provides for extraction of the cloth at reduced pressures between a cooperating drum and an associated wringer all to provide for efficient operation of the extractor.

There is disclosed particularly in FIGS. 39 to 44 an extractor system 925. The extractor system providing for expressing liquids from the flat work 675c exiting from the rinser 710a. It should be again reiterated that the flat work 675c consists of a plurality of continuous sheets of toweling or other pervious cloth arranged in side-by-side relationship to provide the flat work 675. The invention hereinafter disclosed provides for the expression of excess liquid from the flat work 675 all without the problems usually associated with apparatus of this type, particularly the requirement for large, heavy drums, rolls and drive equipment and the attenuated problems of sagging and the improper extraction associated therewith.

The extractor system 925 is provided with a plurality of back-up drums 930 in the form of cylinders arranged in end-to-end relationship mounted for free rotation about a fixed shaft 931, the fixed shaft 931 being suitably connected as at 932 to two spaced-apart upstanding end frames 933 and 934, the end frames provide support for the drums 930 and being connected as hereinafter explained. The cylindrical back-up drums 930 are constructed and arranged for free rotation about the fixed horizontally positioned shaft 931 and therefore all have a common axis, the drums 930 including an inner tube 937 and an outer tube 938, the inner tube 937 and the outer tube 938 being connected by two circular spaced apart end plates 939, the circular end plates 939 having a large central aperture therein, the apertures being aligned in use and the plates 939 being suitably secured to the inner and the outer tubes 937 and 938 respectively such as by welding at 941. The inner tube 937 is counter-sunk to provide a shoulder 942 thereon, for a purpose to be hereinafter explained.

Disposed within each drum 930 adjacent the outer ends thereof are two bearing assemblies 945 including bearing shoes forming inner races 946 and outer races 947 holding therebetween a plurality of ball bearings 948, the bearing shoes forming the inner races 946 being suitably connected to the fixed shaft 931 while the bearing shoes forming the outer races 947 being suitably connected to the inner tube 937 and abutting at one end thereof the shoulders 942. It is therefore seen that each of the back-up drums 930 is mounted for free rotation about the fixed shaft 931.

A spacer sleeve 950 in the form of a tube is positioned about the shaft 931 at both ends of the drums

930, each sleeve 950 abutting the associated bearing shoe forming an inner ball race 946; each sleeve 950 is suitably secured to the shaft 931 to rotate therewith, the spacer sleeve 950 providing the required spacing therewith of the drum 930 along the shaft 931 to prevent movement of the drum 930 in a direction along the longitudinal axis of the shaft 931.

Although the extractor 925 extracts the rinse liquid from the fabric articles in the form of flat work 675c there may be present a certain amount of wash solution entrained therewith and this wash solution must be prevented from contacting the lubrication provided for the ball bearings 948, otherwise, as in the case of the orbital washer 525, the lubrication will be removed from the bearings 948 and cause them to burn out. To that end, an annularly shaped inner oil seal 953 is suitably secured to the inner tube 937 and the bearing shoe forming the outer ball race 947 at each end of the drum 930, each of the inner oil seals 953 having a lip 954 thereon which abuts the associated spacer sleeve 950 and the bearing shoe forming the inner ball race 946 to prevent lubrication from flowing outward. There is also provided two annularly shaped outer oil seals 956 arranged at either end of the drums 930 and abutting the inner oil seals 953, each of the outer oil seals 956 having a lip 957 thereon abutting the associated spacer sleeve 950, the lips 957 facing outwardly from the drum 930 thereby to prevent the introduction of rinse liquid into the area between the bearing shoes defining the races 946 and 947. As may be seen from the foregoing, there has been provided a plurality of spaced-apart back-up drums 930 in the form of cylinders mounted on a common horizontally disposed axis for free rotation thereabout, the number of drums 930 corresponding to the number of lanes of fabric articles making up the flatwork 675c.

There are also provided a plurality of wringer rollers 960, the number of wringer rollers 960 corresponding to the number of drums 930, the wringer rollers 960 being mounted on two spaced-apart driven shafts 961, the driven shafts 961 being parallel to the fixed shaft 931, the axes of rotation of the driven shafts 961 being in the same horizontal plane as the axis of the shaft 931. The shafts 961 are respectively journaled in the end plate 933 for rotation therein and respectively pass through apertures (not shown) in end plate 934 to be connected to a driving mechanism therefor (not shown). The wringer rollers 960 are arranged in two series, each series being comprised of a plurality of rollers in alignment with alternate drums 930. Each of the series of rollers 960 provides alternate of the drums 930 with a corresponding roller 960, and since there are two series of rollers 960 each of the drums 930 is provided with an associated roller 960, adjacent drums 930 having their respective associated roller 960 on opposite sides thereof.

Each roller 960 includes a rubber liner 963 in the form of a tube vulcanized onto a spacer sleeve 965, the spacer sleeve 965 being suitably fastened to the driven shaft 961 for rotation therewith, the spacer sleeve 965 having a longer longitudinal extent than the rubber liner 963. Interposed between each two rollers 960 is a bearing assembly 970, the bearing assemblies 970 being approximately equal to the length of the wringer rollers 960 and hence the drums 930, each bearing as-

sembly comprising a sleeve 971, the sleeve 971 being tubular in shape and counter-sunk at both ends thereof to provide two shoulders 972. An inner bearing shoe 976 is suitably secured to the shaft 961 adjacent to either end of the sleeve 971 and an outer bearing shoe 977 is suitably connected to the sleeve 971 adjacent to either end thereof and in registry with the inner shoe 976, the outer shoe 977 abutting the shoulder 972. Between the inner shoe 976 and the outer shoe 977 are disposed a plurality of needle bearings 978 to enable the shaft 961 to rotate within the bearing assemblies 970, thereby to enable the bearing assemblies 970 to remain stationary while the shafts 960 rotate for a purpose hereinafter explained.

The problems attendant to the contact of the lubrication for the ball bearings 948 are also present with respect to the needle bearings 978 and therefore an inner oil seal 983 is provided at either end of the bearing sleeve 971, the inner oil seals 983 being generally annular in shape and have on their inner edges thereof a lip 984, the lips 984 pointing inwardly toward the needle bearings 978 and contacting the spacer sleeve 965 to prevent the escape of lubrication from between the inner oil seals 983. Abutting the inner oil seals 983 are two outer oil seals 986, the outer oil seals 986 being annular in shape and provided on the inner edges thereof with a lip 987. The lip 987 on the outer oil seals 986 also contacts the sleeve 965 but the lips 987 of the outer oil seals 986 are outwardly directed to prevent the introduction of wash solution or rinse liquid into the area between the inner oil seals 983.

The wringer rollers 960 are urged against the drums 930 by a plurality of pressure yokes 990, there being a pressure yoke 990 for each and every wringer roller 960. The pressure yokes 990 are identically constructed and each comprise a pair of horizontally extending spaced-apart legs 991, the legs 991 being interconnected by a bight portion 992, the bight portion 992 extending in a direction parallel to the axis of the shaft 961 while the legs 991 are generally transverse to the axis of the shaft 961. The legs 991 are further provided with an arcuate surface 993 at the distal ends thereof, the arcuate surfaces 993 having the same radius of curvature as the surface of the bearing assemblies 970 against which they rest. Since the assemblies 970 do not rotate when the shafts 961 rotate no friction is generated between the arcuate surfaces 993 and the assemblies 970 while pressure is being applied to the rollers 960 as hereinafter explained.

Motor action is provided to the pressure yokes 990 by means of a hydraulic system, the system including a pressure header 995 in the form of a pipe positioned parallel to the longitudinal axis of the shafts 961 and the shaft 931 and further including a plurality of lead-in pipes 996, the number of lead-in pipes 996 from the header 995 corresponding in number to the number of pressure yokes 990 present. Each lead-in 996 provides communication between the header 995 and an individual hydraulic cylinder 997, each hydraulic cylinder 997 being provided with a piston 998 connected to the bight 992 of the pressure yoke 990. Operation of the hydraulic cylinders 997 being in the usual manner to move the pressure yokes 990 toward the freely rotatable drums 930. As may be seen therefore, each series of alternate drums 930 has a cor-

responding number of wringer rollers 960 urged thereagainst from the same sides, there being an equal number of pressure yokes 990 on each side of the shaft 931, the net sideways pressure therein being zero. A staggered effect is thereby produced in which a first drum 930 having a roller 960 being urged against it from the right, the next adjacent drum 930 having a roller 960 being urged against it from the left, a third adjacent drum having a roller 960 being urged against it from the right and so on, all resulting in a reduced requirement for the strength of the shafts 961 and the shaft 931, since each shaft 961 only has to be sufficiently strong to provide driving torque for half the usual rollers 960, the shaft 961 can be considerably smaller. Likewise, since the shaft 931 does not have to be sufficiently strong to provide torque to the plurality of drums 930 supported thereon but only be sufficiently strong to support the weight of the drums 930, the shaft 931 can be considerably smaller in diameter than usually encountered in systems of this type.

In general, flat work 675c is introduced onto the drums 930 on the side opposite to the associated roller 960, it being understood that each separate fabric article of toweling is introduced onto a separate drum 930, therefore if there are ten lanes of toweling arranged in a side-by-side relationship, then the ten lanes are introduced unto ten different drums 930. Introduction of the flat work 675c unto the drum as the drum rotates causes the flat work to be carried therearound and thereunder. There is provided a plurality of pad rolls 1005 mounted on shafts 1006, the rolls 1005 being constructed of a soft resilient material and rotating at a speed identical to the speed of rotation of the shafts 961, the rolls 1005 insuring contact of the flat work 675c with the associated drum 930. As the wet flat work 675c is introduced unto the side of the associated drum 930 it is affixed principally by capillary action to the surface of the drum 930 which is smooth and carries therearound to pass upwardly between the drum 930 and the associated wringer roll 960 at a nip 1018 formed thereat. The urging of the wringer roll 960 by the associated pressure yoke 990 against the drum 930 provides for the expression of liquid from the wet flat work 675c disposed therebetween thereby to form flat work 675d having liquid expressed therefrom. There is further provided a plurality of doctor blades 1008, each doctor blade 1008 being positioned above the associated drum 930 and roller 960 and extending parallel to the longitudinal axis of the drum 930, each doctor blade 1008 including a biased edge 1009, the biased edge 1009 facing the associated drum 930 and being sufficiently close thereto thereby to peel the flat work 675d from the surface of the drum 930 as the flatwork 675d passes upwardly between the associated drum 930 and roller 960 through the nip 1018. As may be seen, as the wet flat work 675c passes upwardly between the nip 1018 at the closest most point between the drum 930 and the roller 960, the excess liquid 1019 is expressed therefrom and falls downwardly away from the flat work 675d, the flat work 675d being peeled away from the drum 930 by the doctor blade 1008 and fed thereby onto the surface of the associated roller 960 to be carried therearound and fed therefrom to a dryer 1025.

As may be seen, there has been provided an extractor system 925 in which there are two driven shafts 961 each supporting half the total number of driven wringer rollers 960 thereby requiring smaller shafts 961 to provide the torque for rotation of the rollers 960. The shafts 961 therefore which rotate in opposite directions as shown in FIG. 39, in which the rightmost shaft 961 rotates in a clockwise direction, while the leftmost shaft 961 rotates in a counter-clockwise direction, each support alternately spaced rollers 960 and bearings 970, the rollers 960 on each shaft 961 being associated with alternate drums 930, each drum 930 associated with a roller 960 supported by the rightmost shaft 961 rotates in a counter-clockwise direction while each drum 930 associated with a roller 960 supported by the leftmost shaft 961 rotates in a clockwise direction.

Because the wet flat work 675c is fed upwardly between the associated drum 930 and the associated 20 960, there is no puddle formed between the drum and the roller at the nip 1018 as heretofore encountered in the art where the wet article is usually fed between the two rollers from above, thereby causing the aforementioned puddle to form at the nip and fall therethrough 25 thereby requiring excessive amounts of pressure to be applied to the wringer and the roller to express the proper amount of liquid from the wet article. Concurrent with the requirement for an increase in pressure is a requirement for increased size equipment to exert the 30 pressure. Not only must the shafts 961 be of larger size, but in general also the shaft 931, this clearly being undesirable.

As may be seen particularly in FIG. 41, there is 35 shown a first plurality of rollers 960 corresponding in number to a first set of alternate ones of the drums 930 and arranged for rotation about the common shaft 961, whereas FIG. 42 shows the second plurality of rollers 960 corresponding in number to a second set of alternate ones of the cylinders 930 and arranged for rotation about a third horizontal shafts 961, the shafts 961 and the shafts 931 being disposed in essentially horizontal alignment and parallel to each other. As may 40 be seen for the drums 930 rotating in a clockwise direction, the flat work 675c is fed thereon at the right-hand side thereof as viewed in FIG. 41, while for the drums 930 rotating in a counter-clockwise direction as seen in FIG. 42, the flat work 675c fed thereon is fed from the left-hand side thereof, the flat work 675c in 45 each case being fed on the side of the drum 930 opposite to the associated roller 960. Since the pressure yokes 990 are equal in number and oppositely disposed with respect to the shaft 931, the pressure on the shaft 931 is equalized and therefore the shaft 931 need only 50 be sufficiently large to support the weight of the plurality of drums 930 rotatable thereabout and supported thereby. Since the drums 930 are not power-driven, a slight differential exists in the surface speed relationship between the rollers 960 which are power-driven 55 and the drums 930 and this is due principally to the thickness of the flat work 675. It is therefore necessary to drive the shafts 961 at a slightly higher surface speed than that of the preceding and following processing equipment corresponding to the conveyor 770d and the conveyor associated with the dryer 1025. A trough (not shown) is provided beneath the drums 930 to collect 60 the extracted solution or water 1019 and directed to a 65 dryer 1025.

waste disposal or a heat recovery system or to use the extracted water 1019 as a supply to other phases of the entire system.

In the typical industrial extractor unit previously in use, both the drums and the wringer rollers are driven thereby requiring large shafts for each of them, whereas in the present invention by maintaining the drums 930 in a freely rotatable condition, the shaft 931 supporting the drum 930 is not required to be exceedingly large and, therefore, the problems of increased weight are not encountered. In an industrial unit, wherein perhaps ten lanes of toweling are simultaneously processed, the length of the shafts 931 and 961 are such as to encounter bowing if heavy shafts are used thereby to cause liquid in the lanes of toweling in the center of the unit not to be properly extracted.

The following actual example shows the improved action of the present invention. A 12 inch wide towel, 27 inches long weighs 23 drams in the dry state. Thoroughly saturated, this section of toweling weighs 91 drams. When extracted by the usual method in which the toweling is fed downwardly between driven drum rollers and driven wringer rollers, this same piece of toweling weighs 56 drams after extraction; however, when extracted by the method and apparatus as hereinbefore described, the same section of toweling weighs 45 drams. Therefore, it is clearly seen that 15 to 20 percent better extraction is possible with the method and apparatus of the present invention.

It is seen therefore that there has been provided apparatus and method for expressing liquid from a plurality of series of fabric articles such as flat work 675c comprised of lanes of toweling arranged in side-by-side relationship, the apparatus including a plurality of freely rotatable drums 930 equal in number to the plurality of series of lanes of fabric articles of flat work 675c, the drums 930 being arranged in an end-to-end relationship for rotation about a first essentially horizontal common axis or shaft 931, a first plurality of driving rollers 960 corresponding in number to a first set of alternate ones of the drums 930 and arranged for rotation about a second essentially horizontal common shaft 961 disposed on one side of the drums 930 and in substantial horizontal alignment and substantially parallel to the first shaft 931, a second plurality of rollers 960 corresponding in number to a second set of alternate ones of the drums 930 and arranged for rotation about a third essentially horizontal common shaft 961 disposed on the other side of the rollers 930 and in substantial horizontal alignment and substantially parallel to the first shaft 930 and second shaft 961, a first plurality of feed structures 1005 equal in number to the first set of rollers 930 for feeding the corresponding series of flat work 675c respectively onto the drums 930 in the first set of drums 930 on the sides thereof opposite the associated rollers 960 and downwardly and therearound and upwardly between the drum 930 in the first set of the drums 930 and the associated rollers 960, a second plurality of first feed structures 1005 equal in number to the second set of drums 930 for feeding the corresponding series of flat work 675c respectively onto the drums 930 in the second set of the drums 930 on the sides thereof opposite the associated rollers 960 and downwardly and therearound and upwardly between the drums 930 in the second set of

drums 930, first motor means, in the form of the pressure yokes 990 for urging the first plurality of rollers 960 toward the first set of drums 930 to press the flat work 675c disposed therebetween for expressing the liquid 1019 therefrom, second motor means in the form of pressure yokes 990, for urging the second plurality of rollers 960 toward the second set of drums 930 to press the flat work 675 disposed therebetween for expressing the liquid 1019 therefrom, a first plurality of second feed structures equal in number to the first plurality of rollers 960 for feeding the associated flat work 675d from the first plurality of driving rollers on the sides thereof opposite said first set of drums 930, and a second plurality of second feed structures equal in number to the second plurality of rollers 960 for feeding the associated flat work 675d from the second plurality of rollers 960 on the sides thereof opposite the second set of drums 930, to express liquid 1019 from the flat work 675c downwardly between the portion of the flat work disposed on the associated drums 930 and adjacent exposed side of the associated roller 960.

As may be seen from FIG. 3, the flat work 675d leaving the associated rollers 960 is directed into a dryer 1025, the dryer 1025 including a conveyor 1030 provided with an endless belt 1031 driven by a drive sprocket 1033 supported by a drive shaft 1034, the conveyor 1030 further including an idler sprocket 1036 supported on a shaft 1037, the drive sprocket 1033 and the idler sprocket 1036 providing support for the endless belt 1031 and maintaining the belt taut. There is also provided a plurality of gas burners 1040, the burners being longitudinally spaced apart along length of the conveyor 1030, the conveyor 1030 proceeding in an upwardly inclined direction of travel from the left to the right as viewed in FIG. 3. Three is also shown a hood 1042 for collecting the hot gases emanating from the flat work 675d as it is transported along the predetermined path defined by the conveyor past the gas burners 1040, the hood being disposed over and around the conveyor 1030 and including at the right-hand end thereof a chute or chimney 1043 for conveying the hot gases away from the dryer 1025. At the furthest right-handmost portion of the dryer 1025 there is further provided a discharge platform 1045 having an end plate 1046 thereon, the discharge platform 1045 being adapted to receive the dried flat work, designated 675e, as it is discharged from the conveyor 1030.

As may be seen, there has been provided a complete industrial washing system, the system including a soil-loosening apparatus 105, an orbital washer 525, a rinsing unit 710, a time delay conveyor 905, a further rinsing unit 710a, an expressing unit 925 and a dryer 1025, all being combined to produce an integrated system for the industrial washing of pervious cloth articles and particularly for the industrial washing and processing of pervious cloth in the form of tightly wound, multi-layer rolls of toweling for use in continuous towel dispensing cabinets.

While there has been described what is at present considered to be the preferred embodiment of the invention, it will be understood that various modifications may be made therein and it is intended to cover in the appended claims all such modifications as fall within the true spirit and scope of the invention.

What is claimed is:

1. Apparatus for loosening soil from a mass of pervious cloth comprising a foraminous conveyor including a plurality of spaced-apart tubes coated on the outside thereof with a vinyl plastic resin for transporting the mass of pervious cloth, a crib surrounding said conveyor for retaining the mass of pervious cloth thereon, mechanism associated with said crib for applying a wash solution to the mass of pervious cloth, said foraminous conveyor facilitating the continual draining therethrough and from said crib of excess wash solution from the mass of pervious cloth transported by said foraminous conveyor, said mechanism serving to maintain the surfaces of the pervious cloth wet for a time sufficient to saturate the pervious cloth, whereby to loosen the soil from the pervious cloth.

2. The apparatus set forth in claim 1, wherein said foraminous conveyor includes a plurality of spaced-apart slats.

3. The apparatus set forth in claim 1, and further including drive mechanism operatively connected to said conveyor for causing the same to travel in a closed loop, thereby to transport the mass of pervious cloth through said crib from one end thereof to the other end thereof.

4. The apparatus set forth in claim 1, wherein said crib having two spaced openings therein, one of said openings serving as a loading port for introducing the mass of pervious cloth into said crib and the other of said openings serving as a discharge port for the exiting of the mass of pervious cloth from said crib.

5. The apparatus set forth in claim 1, wherein the surfaces of said crib exposed to the wash solution are stainless steel.

6. The apparatus set forth in claim 1, wherein said crib comprises a plurality of juxtaposed sections with the endmost sections being provided respectively with a loading port and a discharge port, thereby to facilitate easy addition of sections thereto and removal of sections therefrom to change the capacity thereof.

7. The apparatus set forth in claim 1, wherein the wash solution applying mechanism is positioned above the mass of pervious cloth.

8. The apparatus set forth in claim 1, wherein said wash solution applying mechanism is adapted to apply the wash solution as a continuous cascade to the mass of pervious cloth.

9. The apparatus set forth in claim 1, wherein said wash solution applying mechanism includes a trough positioned above the mass of pervious cloth, and further includes means for introducing wash solution into said trough to overflow the same and onto the mass of pervious cloth due to the force of gravity without the requirement of a pressure head.

10. The apparatus set forth in claim 1, and further comprising apparatus associated with said crib for recirculating to said wash solution applying mechanism the excess wash solution drained from said crib.

11. The apparatus set forth in claim 1, and further comprising apparatus associated with said crib for automatically recirculating to said wash solution applying mechanism the excess wash solution drained from said crib.

12. Apparatus for loosening soil from a mass of randomly arranged, tightly wound, multi-layer rolls of pervious cloth comprising a foraminous conveyor for

transporting the mass of tightly wound rolls, a crib surrounding said conveyor retaining the mass of tightly wound rolls thereon, mechanism associated with said crib for periodically applying a wash solution to the mass of tightly wound rolls, said foraminous conveyor facilitating the continual draining therethrough and from said crib of excess wash solution from the mass of tightly wound rolls transported by said foraminous conveyor, said mechanism serving to maintain the surfaces of the tightly wound rolls wet for a time sufficient to saturate each of the tightly wound rolls to the innermost layer thereof, whereby to loosen the soil from the cloth.

13. Apparatus for loosening soil from a mass of randomly arranged, tightly wound, multi-layer rolls of pervious cloth comprising a foraminous conveyor for supporting and transporting the mass of tightly wound rolls, a crib surrounding said conveyor for retaining the mass of tightly wound rolls thereon and including a loading port and a discharge port, supply mechanism associated with said crib including a trough overlying said conveyor, said supply mechanism operable to produce a cascade of wash solution from said trough directed onto said conveyor and periodically onto the mass of tightly wound rolls supported thereby, operation of said conveyor serving to move the mass of tightly wound rolls from said loading port through the cascade of wash solution to said discharge port, said conveyor and said crib being constructed and arranged for the continual draining of excess solution from the mass of tightly wound rolls on said conveyor during the passage thereof from said loading port to said discharge port, the periodic application of the cascade of wash solution to the mass of tightly wound rolls during the transport thereof by said conveyor serving to maintain the surfaces of the tightly wound rolls wet for a time sufficient to saturate the innermost layers thereof, whereby substantially to loosen all of the soil disposed on and in the pervious cloth during the transportation thereof through said crib on said conveyor.

14. The apparatus set forth in claim 13, wherein said trough has a length substantially equal to the width of said conveyor within said crib.

15. The apparatus set forth in claim 13, wherein said trough has a length substantially equal to the width of said conveyor within said crib, said trough being disposed with the longer dimension thereof generally transverse to the direction of movement of said conveyor.

16. The apparatus set forth in claim 13, wherein said trough has impervious sides and bottom, thereby to cause wash solution introduced therein to overflow the sides thereof to form the cascade of wash solution.

17. The apparatus set forth in claim 13, wherein said trough is V-shaped in cross section and has on the upper edges of the sides thereof inwardly turned flanges, thereby to cause wash solution introduced therein smoothly to overflow said upper edges to flow along the sides thereof to form at the bottom thereof the cascade of wash solution.

18. Apparatus for loosening soil from a mass of pervious cloth comprising a foraminous conveyor for supporting and transporting a mass of pervious cloth, a crib surrounding said conveyor for retaining the mass of pervious cloth thereon and including a loading port

and a discharge port, supply mechanism associated with said crib an including a trough overlying said conveyor, said supply mechanism being operable to produce a cascade of wash solution from said trough directed onto said conveyor and periodically onto the mass of pervious cloth supported thereby, motor mechanism connected to said trough for reciprocating said trough along a path overlying said conveyor, operation of said conveyor serving to move the mass of pervious cloth from said loading port through the cascade of wash solution moving in said reciprocal path to said discharge port, said conveyor and said crib being constructed and arranged for the continual draining of excess wash solution from the mass of pervious cloth on said conveyor during the passage thereof from said loading port to said discharge port, the periodic application of the cascade of wash solution to the mass of pervious cloth during the transport thereof by said conveyor serving to maintain the surfaces of the cloth wet for a time sufficient to saturate the pervious cloth, whereby substantially to loosen all of the soil disposed on and in the cloth during the transportation thereof through said crib on said conveyor.

19. The apparatus set forth in claim 18, wherein said reciprocal path is in the direction of movement of said conveyor.

20. Apparatus for loosening soil from a mass of pervious cloth comprising a foraminous conveyor for supporting and transporting a mass of pervious cloth, a crib surrounding said conveyor for retaining the mass of pervious cloth thereon and including a loading port and a discharge port, supply mechanism associated with said crib and including a trough overlying said conveyor, said supply mechanism being operable to produce a cascade of wash solution from said trough directed onto said conveyor and the mass of pervious cloth supported thereby, operation of said conveyor serving to move the mass of pervious cloth from said loading port through the cascade of wash solution to said discharge port, said conveyor and said crib being constructed and arranged for the continual draining of excess wash solution from the mass of pervious cloth on said conveyor during the passage thereof from said loading port to said discharge port, apparatus for collecting the drained wash solution and recirculating the same to said supply mechanism, means including apparatus for mixing water and wash additives for adding make-up wash solution to the drained wash solution in response to depletion of the drained wash solution to maintain substantially constant in volume the cascade of wash solution directed onto said conveyor and the mass of pervious cloth supported thereby, the application of the cascade of wash solution to the mass of pervious cloth during the transport thereof by said conveyor serving to maintain the surfaces of the cloth wet for a time sufficient to saturate the cloth, whereby substantially to loosen all of the soil disposed on and in the cloth during the transportation thereof through said crib on said conveyor.

21. The apparatus set forth in claim 20, wherein said means for adding make-up wash solution to the drained wash solution operates automatically.

22. The apparatus set forth in claim 20, wherein the make-up wash solution added to the drained wash solution is essentially the same as the wash solution in the

cascade of wash solution directed on to said conveyor and the mass of pervious cloth supported thereby.

23. The apparatus set forth in claim 20, wherein said means for adding make-up wash solution includes apparatus for mixing water and liquid additives to provide the make-up wash solution.

24. The apparatus set forth in claim 20, wherein said means for adding make-up wash solution include apparatus for mixing water and solid additives to provide the make-up wash solution.

25. Apparatus for loosening soil from a mass of randomly arranged, tightly wound, multilayer rolls of pervious cloth comprising a foraminous conveyor for supporting and transporting the mass of tightly wound rolls, a crib surrounding said conveyor for retaining the mass of tightly wound rolls thereon and including a loading port and a discharge port, a plurality of supply mechanisms associated with said crib and including a plurality of troughs overlying said conveyor, said supply mechanisms being operable to produce a plurality of cascades of wash solution from said plurality of troughs directed onto said conveyor and periodically onto the mass of tightly wound rolls supported thereby,

15 20 25 30 35 40 45 50 55 60 65

operation of said conveyor serving to move the mass of tightly wound rolls from said loading port through the plurality of cascades of wash solution to said discharge port, said conveyor and said crib being constructed and arranged for the continual draining of excess wash solution from the mass of tightly wound rolls on said conveyor during the passage thereof from said loading port to said discharge port, the periodic application of the plurality of cascades of wash solution to the mass of tightly wound rolls during the transport thereof by said conveyor serving to maintain the surfaces of the cloth wet for a time sufficient to saturate the cloth to the innermost layer thereof whereby substantially to loosen all of the soil disposed on and in the cloth during the transportation thereof through said crib on said conveyor.

26. The apparatus set forth in claim 25, wherein each of said troughs has a length substantially equal to the width of said conveyor within said crib.

27. The apparatus set forth in claim 25, wherein each of said troughs has a length substantially equal to the width of said conveyor within said crib, said troughs being disposed with the longer dimension thereof generally transverse to the direction of movement of said conveyor.

28. The apparatus set forth in claim 25, wherein each of said troughs has impervious sides and bottom, thereby to cause wash solutions introduced therein to overflow the sides thereof to form the cascades of wash solution.

29. The apparatus set forth in claim 25, wherein each of said troughs is V-shaped in cross section and has on the upper edges of the sides thereof inwardly-turned flanges, thereby to cause wash solutions introduced therein smoothly to overflow said upper edges to flow along the sides thereof to form at the bottom thereof the cascades of wash solutions.

30. The apparatus set forth in claim 25, wherein each of said troughs has a length substantially equal to the width of said conveyor within said crib, said trough being disposed with the longer dimension thereof generally transverse to the direction of movement of

said conveyor, said troughs being longitudinally spaced-apart along the direction of movement of said conveyor.

31. Apparatus for loosening soil from a mass of randomly arranged, tightly wound, multilayer rolls of pervious cloth comprising a foraminous conveyor for supporting and transporting the mass of tightly wound rolls, a crib surrounding said conveyor for retaining the mass of tightly wound rolls thereon and including a loading port and a discharge port, a plurality of supply mechanisms associated with said crib and including a plurality of troughs overlying said conveyor, said supply mechanisms being operable to produce a plurality of cascades of wash solution from said plurality of troughs directed onto said conveyor and periodically onto the mass of tightly wound rolls supported thereby, motor mechanism connected to said troughs for respectively reciprocating said troughs along longitudinally aligned paths overlying said conveyor thereby to form a plurality of zones, operation of said conveyor serving to move the mass of tightly wound rolls from said loading port to said discharge port through said plurality of zones formed by the cascades of wash solution, said conveyor and said crib being constructed and arranged for the continual draining of excess wash solution from the mass of tightly wound rolls on said conveyor during the passage thereof from said loading port to said discharge port, and apparatus associated with each zone for collecting excess wash solution draining from the mass of tightly wound rolls transported by said conveyor through each of said zones and for recirculating to the associated one of said troughs the excess wash solution so collected, and the application of the plurality of cascades of wash solution to the mass of tightly wound rolls during the transport thereof by said conveyor through said zones serving to maintain the surfaces of the rolls wet for a time sufficient to saturate each of the tightly wound rolls to the innermost layer thereof upon exiting from the last of said zones, whereby substantially to loosen all of the soil disposed on and in the cloth forming the tightly wound rolls during the transportation thereof through said crib on said conveyor.

32. The apparatus set forth in claim 31, wherein said reciprocal paths are in the direction of movement of said conveyor.

33. Apparatus for loosening soil from a mass of randomly arranged, tightly wound, multi-layer rolls of pervious cloth comprising a foraminous conveyor for supporting and transporting the mass of tightly wound rolls, a crib surrounding said conveyor for retaining the mass of tightly wound rolls thereon and including a loading port and a discharge port, a plurality of supply mechanisms associated with said crib and including a plurality of troughs overlying said conveyor, said supply mechanisms being operable to produce a plurality of cascades of wash solution from said plurality of troughs directed onto said conveyor and the mass of tightly wound rolls supported thereby, said troughs being respectively reciprocable along longitudinally aligned paths overlying said conveyor thereby to form a plurality of zones, operation of said conveyor serving to move the mass of tightly wound rolls from said loading port to said discharge port through said plurality of zones formed by the cascades of wash solution, said

conveyor and said crib being constructed and arranged for the continual drainage of excess wash solution from the mass of tightly wound rolls on said conveyor during the passage thereof from said loading port to said discharge port, apparatus associated with each zone for collecting excess wash solution draining from the mass of tightly wound rolls transported by said conveyor through each of said zones and for recirculating to the associated one of said troughs the excess wash solution so collected, and a plurality of temperature control devices for controlling the temperature of the plurality of cascades of wash solution thereby to apply the wash solution in certain of said zones at an elevated temperature with respect to the wash solution in an adjacent one of said zones sequentially to subject the mass of tightly wound rolls to wash solutions at different temperatures to induce thermal shock in each of the tightly wound rolls, the application of the plurality of cascades of wash solution to the mass of tightly wound rolls during the transport thereof by said conveyor through said zones serving to maintain the surfaces of the rolls wet for a time sufficient to saturate each of the tightly wound rolls to the innermost layer thereof upon exiting from the last of said zones, whereby substantially to loosen all of the soil disposed on and in the cloth forming the tightly wound rolls during the transportation thereof through said crib on said conveyor.

34. The apparatus set forth in claim 33, wherein said temperature control mechanism is adapted to provide wash solution to said supply mechanisms at a temperature in the range from about 50° to about 200° F.

35. The apparatus set forth in claim 33, wherein the wash solution supplied to said certain of said zones is at a temperature in the range from about 150° to about 200° F.

36. The apparatus set forth in claim 33, wherein the wash solution supplied to an adjacent one of said zones is at a temperature of about 50° F.

37. The apparatus set forth in claim 33, wherein the wash solution supplied to the last of said zones is at a temperature of about 190° F.

38. Apparatus for loosening soil from a mass of randomly arranged, tightly wound, multilayer rolls of pervious cloth comprising a foraminous conveyor for supporting and transporting the mass of tightly wound rolls, a crib surrounding said conveyor for retaining the mass of tightly wound rolls thereon and including a loading port and a discharge port, a plurality of supply mechanisms associated with said crib and including a plurality of troughs overlying said conveyor, said supply mechanisms being operable to produce a plurality of cascades of wash solution from said plurality of troughs directed onto said conveyor and the mass of tightly wound rolls supported thereby, said troughs being respectively reciprocable along longitudinally aligned paths overlying said conveyor thereby to form a plurality of zones, operation of said conveyor serving to move the mass of tightly wound rolls from said loading port to said discharge port through said plurality of zones formed by the cascades of wash solution, said conveyor and said crib being constructed and arranged for the continual draining of excess wash solution from the mass of tightly wound rolls on said conveyor during the passage thereof from said loading port to said discharge port, apparatus associated with each zone for

collecting excess wash solution draining from the mass of tightly wound rolls transported by said conveyor through each of said zones and for recirculating to the associated one of said troughs the excess wash solution so collected, and means including apparatus for mixing water and wash additives for adding make-up wash solution respectively to the drained wash solution from each zone in response to depletion of the drained wash solution from the respective zone to maintain substantially constant in volume each of the cascades of wash solution directed onto said conveyor and the mass of tightly wound rolls supported thereby, the application

of the plurality of cascades of wash solution to the mass of tightly wound rolls during the transport thereof by said conveyor through said zones serving to maintain the surfaces of the rolls wet for a time sufficient to saturate each of the tightly wound rolls to the innermost layer thereof upon exiting from the last of said zones, whereby substantially to loosen all of the soil disposed on and in the cloth forming the tightly wound rolls during the transportation thereof through said crib on said conveyor.
